ABSTRACT

[21] Appl. No.: 08/902,102

A device for determining deterioration of an air-fuel ratio sensor according to the present invention includes: an air-fuel ratio sensor provided in an exhaust passage of an internal combustion engine, the air-fuel ratio sensor being capable of continuously detecting a broad range of air-fuel ratios including a stoichiometric air-fuel ratio; an air-fuel ratio feedback control circuit for feedback controlling a fuel injection amount based on a difference between an output of the air-fuel ratio sensor and a target output corresponding to a target air-fuel ratio so that an air-fuel ratio of a gaseous mixture substantially equals the target air-fuel ratio, the gaseous mixture being supplied to the engine; a variation cumulative value calculation circuit for cumulating, while the air-fuel ratio feedback control is being performed by the air-fuel ratio feedback control circuit, a variation Δ F in a fuel injection correction amount, thereby calculating a cumulative variation value $\Sigma\Delta$ F for a predetermined period; and a deterioration determination circuit for determining that the air-fuel ratio sensor is deteriorated when the cumulative variation value $\Sigma\Delta$ F calculated by the variation cumulative value calculation circuit exceeds a predetermined value.

**DEVICE FOR DETERMINING
DETERIORATION OF AIR-FUEL RATIO
SENSOR**

BACKGROUND OF THE INVENTION

1. Field of the Invention

The present invention relates to a device for determining the deterioration of an air-fuel (A/F) ratio sensor employed in an air-fuel ratio control device of an internal combustion engine in order to control the air-fuel ratio (i.e., the ratio at which air and fuel are mixed together) at a desired value, by supplying fuel in accordance with the amount of air intake. More specifically, the present invention relates to a device for determining the deterioration of an A/F ratio sensor located upstream of an exhaust gas purification catalyst for A/F feedback control, the A/F ratio sensor being capable of linearly detecting the air-fuel ratio.

2. Description of the Related Art

Conventionally, automobile engines employ a three-way catalyst as means for purifying their exhaust gas, where the three-way catalyst simultaneously promotes the oxidation of the unburnt components (hydrocarbons (HC), and/or carbon monoxide (CO)) and the reduction of nitrogen oxides (NO). In order to enhance the oxidation and/or reduction ability of the three-way catalyst, it is necessary to control the A/F ratio (which indicates the state of combustion within the engine) to be in the vicinity (or "window") of a theoretical or stoichiometric air-fuel ratio. Thus, the fuel injection control for an engine is typically achieved by means of an O₂ sensor (FIG. 1) for detecting whether the A/F ratio is "rich" (implying a relatively large supply of fuel) or "lean" (implying a relatively small supply of fuel) as compared to the stoichiometric A/F ratio, so that the amount of fuel supplied is corrected based on the detected residual oxygen concentration in the exhaust gas (i.e., the output of the O₂ sensor).

In recent years, internal combustion engines have been developed which are capable of controlling the A/F ratio so that the three-way catalyst therein can maintain a constant purification ability. Behind this concept is a fact that a three-way catalyst, which adsorbs oxygen within exhaust gas when the A/F ratio of the exhaust gas is in a lean state and releases the adsorbed oxygen when the A/F ratio of the exhaust gas is in a rich state (such function is referred to as "O₂ storage function"), has a limited O₂ storage capability. Therefore, in order to allow a three-way catalyst to fully utilize its O₂ storage capability, it is essential to maintain the amount of oxygen stored in the catalyst at a predetermined value, e.g., half of its maximum oxygen storage capacity, so that the three-way catalyst is kept ready for an on-coming lean condition or rich condition in the A/F ratio of the exhaust gas. By thus maintaining the amount of oxygen stored in the catalyst at such a predetermined value, the three-way catalyst can exhibit constant O₂ adsorbing or releasing capabilities, and hence constant oxidation or reduction capabilities.

Such an internal combustion engine capable of controlling the amount of O₂ stored in a catalyst for maintaining the purification capabilities of the catalyst typically employs an A/F ratio sensor. Such an A/F ratio sensor exhibits a characteristic curve as shown in FIG. 2, and is capable of linearly detecting a broad range of A/F ratios including the stoichiometric A/F ratio. Specifically, the A/F ratio sensor is employed for attaining a feedback control which is based on proportional and integral (PI) operations that can be expressed as follows:

(Next fuel injection correction amount)= $K_p \times$ (fuel difference in the current session)+ $K_s \times \Sigma$ (fuel differences in all past sessions)

where the term "fuel difference" is defined as:

5 (the amount of fuel actually burnt within cylinders)—(the target fuel amount to be burnt within cylinders with a stoichiometric amount of air intake), where the term (the amount of fuel actually burnt within cylinders) is defined as (detected air amount)/(detected A/F ratio); the coefficient K_p represents a gain for the proportional term; and

10 the coefficient K_s represents a gain for the integral term. Thus, the fuel injection correction amount is constantly calculated in the context of feedback control.

15 As seen from the above, the equation for calculating the fuel injection correction amount includes a proportional term prefixed by the coefficient K_p and an integral term prefixed by the coefficient K_s. The proportional term is a component for maintaining the A/F ratio at the stoichiometric A/F ratio, whereas the integral term is a component for eliminating an offset. The integral term serves to maintain the amount of O₂ stored in the catalyst at a constant value. For example, if lean gas is generated in response to an abrupt acceleration, the integral term causes rich gas to be generated so as to cancel the effect of the lean gas.

20 As described above, the A/F ratio feedback control which is based on the output voltage of an A/F ratio sensor is performed so as to increase the fuel injection correction amount as an offset of the output voltage from a target voltage (i.e., a voltage corresponding to the stoichiometric A/F ratio) increases. However, as the A/F ratio sensor deteriorates due to the heat of the exhaust gas and/or the poisonous effects of the lead component, phosphorus component, etc. within the fuel and/or lubrication oil, the 25 response characteristics (i.e., reaction speed at which the sensor can follow actual changes in the A/F ratio) of the A/F ratio sensor decreases, thereby making it difficult to achieve the desired A/F ratio feedback control.

25 A conventional device for detecting the deterioration of an A/F ratio sensor is disclosed in, for example, Japanese Laid-Open Patent Publication No. 5-106486. The disclosed device for determining the deterioration of an A/F ratio sensor relies on the output of an A/F ratio sensor that is capable of continuously detecting the A/F ratio, which may 30 take any value within a broad range of A/F ratios including the stoichiometric value. The device learns respective feedback correction mounts for a target A/F ratio set at the stoichiometric A/F ratio and for a target A/F ratio set at a value different from the stoichiometric A/F ratio (e.g., a lean 35 A/F ratio) based on the output of the A/F ratio sensor, and determines the deterioration of the A/F ratio sensor based on a difference between the respective learned values.

40 Since the above-described conventional device for detecting the deterioration of an A/F ratio sensor must learn the feedback correction amounts associated with different target A/F ratios (i.e., the stoichiometric value and another value) and compare the learned values, there is a disadvantage in that the deterioration determination often takes a long times. Furthermore, the determination of A/F ratio sensor deterioration by the conventional device is only applicable to an 45 A/F ratio control system whose control is directed to both the stoichiometric A/F ratio and another A/F ratio, erg., a lean A/F ratio. That is, the conventional device is not applicable to a system where the A/F ratio is always controlled toward one target A/F ratio (erg., the stoichiometric A/F ratio). Moreover, the conventional device relies on the 50 fact that a relatively large fluctuation occurs in the output of

deteriorated A/F ratio sensors while performing an A/F control on the lean side (as opposed to the stoichiometric A/F ratio) That is, the determination is dependent on the deterioration or fluctuation that occurs in only a limited control range of the A/F ratio sensor, thereby making it difficult to provide a stable determination of deterioration.

SUMMARY OF THE INVENTION

A device for determining deterioration of an air-fuel ratio sensor according to the present invention includes: an air-fuel ratio sensor provided in an exhaust passage of an internal combustion engine, the air-fuel ratio sensor being capable of continuously detecting a broad range of air-fuel ratios including a stoichiometric air-fuel ratio; air-fuel ratio feedback control means for feedback controlling a fuel injection amount based on a difference between an output of the air-fuel ratio sensor and a target output corresponding to a target air-fuel ratio so that an air-fuel ratio of a gaseous mixture substantially equals the target air-fuel ratio, the gaseous mixture being supplied to the engine; variation cumulative value calculation means for cumulating, while the air-fuel ratio feedback control is being performed by the air-fuel ratio feedback control means, a variation ΔF in a fuel injection correction amount, thereby calculating a cumulative variation value $\Sigma \Delta F$ for a predetermined period; and deterioration determination means for determining that the air-fuel ratio sensor is deteriorated when the cumulative variation value $\Sigma \Delta F$ calculated by the variation cumulative value calculation means exceeds a predetermined value.

Alternatively, the device for determining deterioration of an air-fuel ratio sensor according to the present invention includes: an air-fuel ratio sensor provided in an exhaust passage of an internal combustion engine, the air-fuel ratio sensor being capable of continuously detecting a broad range of air-fuel ratios including a stoichiometric air-fuel ratio; air-fuel ratio feedback control means for feedback controlling a fuel injection amount based on a difference between an output of the air-fuel ratio sensor and a target output corresponding to a target air-fuel ratio so that an air-fuel ratio of a gaseous mixture substantially equals the target air-fuel ratio, the gaseous mixture being supplied to the engine; output cumulative value calculation means for cumulating, while the air-fuel ratio feedback control is being performed by the air-fuel ratio feedback control means, an absolute value of output of the air-fuel ratio sensor or a difference between the output of the air-fuel ratio sensor and the target output, thereby calculating a cumulative output value ΣV for a predetermined period; and deterioration determination means for determining that the air-fuel ratio sensor is deteriorated when the cumulative output value ΣV calculated by the output cumulative value calculation means exceeds a predetermined value.

Alternatively, the device for determining deterioration of an air-fuel ratio sensor according to the present invention includes: an air-fuel ratio sensor provided in an exhaust passage of an internal combustion engine, the air-fuel ratio sensor being capable of continuously detecting a broad range of air-fuel ratios including a stoichiometric air-fuel ratio; air-fuel ratio feedback control means for feedback controlling a fuel injection amount based on a difference between an output of the air-fuel ratio sensor and a target output corresponding to a target air-fuel ratio so that an air-fuel ratio of a gaseous mixture substantially equals the target air-fuel ratio, the gaseous mixture being supplied to the engine; variation cumulative value calculation means for cumulating, while the air-fuel ratio feedback control is being performed by the air-fuel ratio feedback control means,

performed by the air-fuel ratio feedback control means, a variation ΔV in output of the air-fuel ratio sensor, thereby calculating a cumulative variation value $\Sigma \Delta V$ for a predetermined period; and deterioration determination means for determining that the air-fuel ratio sensor is deteriorated when the cumulative variation value $\Sigma \Delta V$ calculated by the variation cumulative value calculation means exceeds a predetermined value.

Alternatively, the device for determining deterioration of an air-fuel ratio sensor according to the present invention includes: an air-fuel ratio sensor provided in an exhaust passage of an internal combustion engine, the air-fuel ratio sensor being capable of continuously detecting a broad range of air-fuel ratios including a stoichiometric air-fuel ratio; air-fuel ratio feedback control means for feedback controlling a fuel injection amount based on a difference between an output of the air-fuel ratio sensor and a target output corresponding to a target air-fuel ratio so that an air-fuel ratio of a gaseous mixture substantially equals the target air-fuel ratio, the gaseous mixture being supplied to the engine; variation cumulative value calculation means for cumulating, while the air-fuel ratio feedback control is being performed by the air-fuel ratio feedback control means, a variation ΔF in a fuel injection correction amount and a variation ΔV in output of the air-fuel ratio sensor, thereby respectively calculating a cumulative variation value $\Sigma \Delta F$ and a cumulative variation value $\Sigma \Delta V$ for a predetermined period; and deterioration determination means for determining if the air-fuel ratio sensor is deteriorated based on a ratio between the cumulative variation value $\Sigma \Delta F$ and the cumulative variation value $\Sigma \Delta V$ calculated by the variation cumulative value calculation means.

Alternatively, the device for determining deterioration of an air-fuel ratio sensor according to the present invention includes: an air-fuel ratio sensor provided in an exhaust passage of an internal combustion engine, the air-fuel ratio sensor being capable of continuously detecting a broad range of air-fuel ratios including a stoichiometric air-fuel ratio; air-fuel ratio feedback control means for feedback controlling a fuel injection amount based on a difference between an output of the air-fuel ratio sensor and a target output corresponding to a target air-fuel ratio so that an air-fuel ratio of a gaseous mixture substantially equals the target air-fuel ratio, the gaseous mixture being supplied to the engine; variation cumulative value calculation means for cumulating, while the air-fuel ratio feedback control is being performed by the air-fuel ratio feedback control means, output V of the air-fuel ratio sensor and a variation ΔV in the output of the air-fuel ratio sensor, thereby respectively calculating a cumulative output value ΣV and a cumulative variation value $\Sigma \Delta V$ for a predetermined period; and deterioration determination means for determining if the air-fuel ratio sensor is deteriorated based on a ratio between the cumulative output value ΣV and the cumulative variation value $\Sigma \Delta V$ calculated by the variation cumulative value calculation means.

In one embodiment of the invention, the device for determining the deterioration of an air-fuel ratio sensor further includes variation cumulative value calculation means for cumulating, while the air-fuel ratio feedback control is being performed by the air-fuel ratio feedback control means, a variation ΔF in a fuel injection correction amount and a variation ΔV in output of the air-fuel ratio sensor, thereby respectively calculating a cumulative variation value $\Sigma \Delta F$ and a cumulative variation value $\Sigma \Delta V$ for a predetermined period, wherein the deterioration determination means determines if the air-fuel ratio sensor is

deteriorated based on a ratio between the cumulative output value ΣV and the cumulative variation value $\Sigma \Delta V$ and a ratio between the cumulative variation value $\Sigma \Delta FT$ and the cumulative variation value $\Sigma \Delta V$.

In another embodiment of the invention, the deterioration determination means determines if the air-fuel ratio sensor is deteriorated based on a product of a ratio between the cumulative output value ΣV and the cumulative variation value $\Sigma \Delta V$ and a ratio between the cumulative variation value $\Sigma \Delta FT$ and the cumulative variation value $\Sigma \Delta V$.

Thus, in an A/F ratio control apparatus employing an A/F ratio sensor capable of continuously detecting an A/F ratio in a broad range of values including the stoichiometric A/F ratio, the invention described herein advantageously provides a device for achieving the early detection of the deterioration of the A/F ratio sensor without relying on the sensor characteristics outside the control range for the stoichiometric value.

This and other advantages of the present invention will become apparent to those skilled in the art upon reading and understanding the following detailed description with reference to the accompanying figures.

BRIEF DESCRIPTION OF THE DRAWINGS

FIG. 1 is a graph illustrating the relationship between an A/F ratio and an output voltage of an O_2 sensor.

FIG. 2 is a graph illustrating the relationship between an A/F ratio and an output voltage of A/F ratio sensor.

FIG. 3 is a general view showing an electronically-controlled internal combustion engine incorporating an A/F ratio sensor and an A/F ratio control device, where the A/F ratio sensor is to be tested for deterioration by the A/F ratio sensor deterioration detection device according to the present invention.

FIG. 4 is a block diagram showing an exemplary hardware structure of an engine ECU (electronics control unit) of the electronically-controlled internal combustion engine shown in FIG. 3.

FIG. 5 is a flow diagram illustrating the procedure of an INNER-CYLINDER AIR AMOUNT ESTIMATION AND TARGET INNER-CYLINDER FUEL AMOUNT CALCULATION routine.

FIG. 6 is a diagram showing estimated inner-cylinder air amounts relative to calculated target inner-cylinder fuel amounts.

FIG. 7 is a flow diagram illustrating the procedure of the A/F RATIO FEEDBACK CONTROL routine.

FIG. 8 is a flow diagram illustrating the procedure of the FUEL INJECTION CONTROL routine.

FIG. 9A is a graph schematically illustrating the relationship between an output voltage V_{AF} of an A/F ratio sensor (solid line) and an ideal output voltage of the A/F ratio sensor reflecting the actual A/F ratio (broken line), illustrating an A/F ratio sensor with normal response characteristics.

FIG. 9B is a graph schematically illustrating the relationship between an output voltage V_{AF} of an A/F ratio sensor (solid line) and an ideal output voltage of the A/F ratio sensor reflecting the actual A/F ratio (broken line), illustrating an A/F ratio sensor with deteriorated response characteristics.

FIG. 10A illustrates the output V_{AF} of a high-response A/F ratio sensor (broken line) and the out-put V_{AF} of a low-response A/F ratio sensor (solid line).

FIG. 10B illustrates exemplary feedback corrections performed for the fuel injection amount (FIC).

FIG. 11A illustrates an exemplary output of an A/F ratio sensor.

FIG. 11B illustrates an exemplary fuel injection correction (FIC) rate based on a feedback control.

FIG. 12 schematically shows the relationship between the response characteristics of an A/F ratio sensor and $P = \Sigma \Delta FT / \Sigma \Delta V$, where $\Sigma \Delta FT$ represents a cumulative value of the variation ΔFT in a FIC amount and $\Sigma \Delta V$ represents a cumulative value of the variation ΔV in the A/F ratio sensor output.

FIG. 13A illustrates the output characteristics of a high-response A/F ratio sensor.

FIG. 13B illustrates the output characteristics of a low-response A/F ratio sensor.

FIG. 14 schematically shows the relationship between the response characteristics of an A/F ratio sensor and a ratio $\Sigma V_m / \Sigma \Delta V_n$, where ΣV_m represents a cumulative value of the absolute values of the A/F ratio sensor output and $\Sigma \Delta V_n$ represents a cumulative value of the variation ΔV_n in the A/F ratio sensor output.

FIG. 15 is a flow diagram illustrating the A/F ratio sensor OUTPUT DETERIORATION (MALFUNCTIONING) DETERMINATION routine for determining the deterioration 25 of an A/F ratio sensor output according to Example 1 of the present invention.

FIG. 16 is a flow diagram illustrating the A/F ratio sensor OUTPUT DETERIORATION (MALFUNCTIONING) DETERMINATION routine for determining the deterioration 30 of an A/F ratio sensor output according to Example 2 of the present invention.

FIG. 17 is a flow diagram illustrating the A/F ratio sensor OUTPUT DETERIORATION (MALFUNCTIONING) DETERMINATION routine for determining the deterioration 35 of an A/F ratio sensor output according to Example 3 of the present invention.

FIG. 18 is a flow diagram illustrating the A/F ratio sensor OUTPUT DETERIORATION (MALFUNCTIONING) DETERMINATION routine for determining the deterioration 40 of an A/F ratio sensor output according to Example 4 of the present invention.

FIG. 19 is a flow diagram illustrating the A/F ratio sensor OUTPUT DETERIORATION (MALFUNCTIONING) DETERMINATION routine for determining the deterioration 45 of an A/F ratio sensor output according to Example 5 of the present invention.

FIG. 20 is a flow diagram illustrating the A/F ratio sensor OUTPUT DETERIORATION (MALFUNCTIONING) DETERMINATION routine for determining the deterioration 50 of an A/F ratio sensor output according to Example 6 of the present invention.

FIG. 21 is a flow diagram illustrating the A/F ratio sensor OUTPUT DETERIORATION (MALFUNCTIONING) DETERMINATION routine for determining the deterioration 55 of an A/F ratio sensor output according to Example 7 of the present invention.

DESCRIPTION OF THE PREFERRED EMBODIMENTS

Hereinafter, the present invention will be described by way of illustrative examples, with reference to the accompanying figures.

First, an exemplary internal combustion engine, to which the A/F ratio sensor deterioration detection device according to the invention is applicable, will be briefly described. FIG.

3 shows an electronically-controlled internal combustion engine 10 incorporating an A/F ratio sensor and an A/F ratio control device, where the A/F ratio sensor is to be tested for deterioration by the A/F ratio sensor deterioration detection device according to the present invention.

Air required for the combustion in the engine is filtered through an air cleaner 2, passed through a throttle body 4, and routed into the air intake tubes of the respective cylinders via a surge tank (intake manifold) 6. The flow amount of the air intake is adjusted by means of a throttle valve 5 provided on the throttle body 4 and measured by an airflow meter 40. The temperature of the air intake is detected by an air intake temperature sensor 43. The pressures within the air intake tubes are detected by a vacuum sensor 41.

The degree of opening of the throttle valve 5 is detected by a throttle opening degree sensor 42. When the throttle valve 5 is in a fully-close state, an idling switch 52 is turned on so that its output, i.e., a throttle-closed signal becomes active. An idling rotation speed control valve (ISCV) 66 is provided in an idling adjustment passage 8 which by-passes the throttle valve 5. The idling rotation speed control valve (ISCV) 66 adjusts the flow of air during idling.

Fuel stored in a fuel tank 10 is pumped by a fuel pump 11 into a fuel pipe 12 so as to be injected into each air intake tube 7.

The fuel is mixed with air within the air intake tube 7. The gaseous mixture is sucked into a combustion chamber 21 of each cylinder 20 (which essentially constitutes the body of the engine) via an air intake valve 24. In the combustion chamber 21, the gaseous mixture is first compressed by means of a piston 23 and then ignited to explode into combustion, whereby kinetic energy is generated. Specifically, the ignition process proceeds as follows: an ignitor 62, receiving an ignition signal, controls the supply of a primary electric current to an ignition coil 63 so that the secondary electric current of the ignition coil 63 is supplied to a spark plug 65 via an ignition distributor 64.

The ignition distributor 64 includes a reference position detection sensor 50 and a crank angle sensor 51. The reference position detection sensor 50 generates a reference position detection pulse for every rotation angle (of the distributor axis) that corresponds to a crank angle (CA) of 720°. The crank angle sensor 51 generates a position detection pulse for every rotation angle (of the distributor axis) that corresponds to 30° CA. The actual velocity of the automobile is detected by a speed sensor 53 which generates output pulses indicating the velocity of the automobile. The engine body (cylinder(s)) 20 is cooled by cooling water introduced into a passage 22. The temperature of the cooling water is detected by a water temperature sensor 44.

The gaseous mixture after combustion is led into an exhaust manifold 30 via an exhaust valve 26 (as exhaust gas) and subsequently into an exhaust tube 34. Attached to the exhaust tube 34 is an A/F ratio sensor 45 for linearly detecting the A/F ratio based on the oxygen concentration within the exhaust gas. Further downstream of the exhaust tube 34, the exhaust system includes a catalytic convertor 38 which accommodates a three-way catalyst for promoting the oxidation of the unburnt components (HC and/or CO) as well as the reduction of nitrogen oxides (NO_x). The exhaust gas is discharged into the atmosphere only after being purified by the catalytic convertor 38.

The exemplary engine performs an A/F ratio sub-feedback control to vary the center of A/F ratio feedback control made with the A/F ratio sensor 45. Downstream of the catalytic convertor 38 is provided an O₂ sensor 46. The O₂ sensor 46 is preferable, but not essential to the present invention.

An engine electronics control unit (hereinafter referred to as the "engine ECU") 70 is a microcomputer system for performing various controls, e.g., fuel injection control (A/F ratio control), ignition timing control, and idling rotation speed control, as well as determination of the deterioration of the response characteristics of the A/F ratio sensor. FIG. 4 is a block diagram showing an exemplary hardware structure of the engine ECU 70. In accordance with programs and various maps stored in a ROM (read only memory) 73, a CPU (central processing unit) 71 receives signals from various sensors 40 to 46 and switches 50 to 53 via an A/D convertor circuit 75 or an input interface circuit 76, performs calculations based on such input signals, and outputs control signals for various actuators based on the calculation results via drive control circuits 77a to 77d. A RAM (random access memory) 74 is used as a temporary data storage means during the calculation/control process. A backup RAM 79 is directly coupled to a battery (not shown) for power supply, so that the RAM 79 can retain necessary data (e.g., various learned values) even while the ignition switch is turned off. The component elements of the engine ECU 70 are interconnected via system buses 72 including address buses, data buses, and control buses.

Hereinafter, an engine control process performed by the engine ECU 70 in an internal combustion engine having the above-described hardware configuration will be described.

Ignition timing control includes determining the overall state of the engine based on signals from various sensors (erg., an engine rotation speed signal from the crank angle sensor 52), deciding the optimum moment for ignition, and sending an ignition signal to the ignitor 62 via the drive control circuit 77b.

Idling rotation speed control includes detecting an idling state based on a throttle-closed signal from the idling switch 52 and a speed signal from the speed sensor 53, comparing the target rotation speed (which is determined by factors such as the engine cooling water temperature signal from the water temperature sensor 44) with the actual engine rotation speed, determining a control amount for achieving the target rotation speed based on the difference between the two, and adjusting the amount of air flow by controlling the ISCV 66 via the drive control circuit 77c. As a result of this control, the optimum idling rotation speed is maintained.

For the sake of describing an A/F ratio control (fuel injection control) system to which the present invention is applicable and describing a process for detecting the response characteristics of an A/F ratio sensor according to the present invention, the procedures of a few related routines are first described below.

FIG. 5 is a flow diagram illustrating the procedure of an INNER-CYLINDER AIR AMOUNT ESTIMATION AND TARGET INNER-CYLINDER FUEL AMOUNT CALCULATION routine, which is executed for every predetermined degrees of the crank angle. First, the air amount MC_i within the relevant cylinder that has been obtained up to the previous call (execution) of this routine and the target inner-cylinder fuel amount FCR_i are both updated. Specifically, at step S102, the MC_i and FCR_i from i calls (of the routine) ago are newly regarded as MC_{i+1} and FCR_{i+1} from i+1 calls ago (where i=0, 1, . . . , n-1). This update is made in order to store the values of the innercylinder air amount MC_i and the target inner-cylinder fuel amount FCR_i for the past n calls of the routine into the RAM 74, and to further calculate MC₀ and FCR₀ as part of the current routine.

Next, at step S104, the current pressure PM of the air intake tube, the current rotation speed NE of the engine, and

the current throttle opening TR are calculated based on the outputs from the vacuum sensor 41, the crank angle sensor 52, and the throttle opening degree sensor 42. Then the inner-cylinder air amount MC_0 , i.e., the amount of air being supplied into the cylinder, is estimated based on the data of PM, NE, and TA (step S106). Although it is generally possible to estimate the inner-cylinder air amount based on PM and NE, the present example further monitors the changes in TA in order to detect a transition state, so that the air amount can be accurately calculated even during transition states.

Next, based on the inner air amount MC_0 and the stoichiometric A/F ratio value AFT, the target fuel amount FCR_0 , which should ideally be supplied into the cylinder to attain a stoichiometric A/F ratio of the gaseous mixture, is derived as follows at step S108:

$$FCR_0 \leftarrow MC_0 / AFT$$

The inner air amount MC_0 and the target fuel amount FCR_0 thus obtained are stored in the RAM 74 as the latest data (i.e., obtained during the current call of the routine) in the format shown in FIG. 6.

Next, an A/F RATIO FEEDBACK CONTROL routine and a FUEL INJECTION ROUTINE will be described.

FIG. 7 is a flow diagram illustrating the procedure of the A/F RATIO FEEDBACK CONTROL routine, which is executed for every predetermined degrees of the crank angle. First, at step S112, it is determined whether or not the conditions for permitting the execution of feedback control (hereinafter referred to as "feedback control-permitting conditions") are satisfied. For example, the feedback control-permitting conditions may not be satisfied during periods of excessively low temperature of the cooling water, starting the engine, periods of increased fuel usage after the engine is started, periods of increased usage of fuel for warming-up the engine, absence of changes in the output signal of the A/F ratio sensor 45, and/or periods of reduced fuel usage; otherwise the feedback control-permitting conditions are considered as being satisfied. If the feedback control-permitting conditions are not satisfied, the fuel injection correction amount FT through feedback control is set at 0 at step S124 and this routine is ended.

If the feedback control-permitting conditions are satisfied, the fuel difference FD_1 (i.e., the difference between the amount of fuel actually burnt within the cylinder and the target inner-cylinder fuel amount), which has been obtained up to the previous call of this routine, is updated. Specifically, at step S114, the FD_i from i calls (of the routine) ago are newly regarded as the FD_{i+1} from $i+1$ calls ago (where $i=0, 1, \dots, m-1$). This update is made in order to store the value of the fuel difference FD_i for the past m calls of the routine into the RAM 74, and to further calculate FD_0 as part of the current routine.

Next, at step S116, the output voltage VAF of the A/F ratio sensor 45 is detected. Then, by referring to the characteristic curve of FIG. 2 based on the output voltage VAF, the current A/F ratio value ABF is determined at step S1180. The characteristic curve of FIG. 2 is previously stored in the ROM 73 in the form of a map.

Next, based on the inner air amount MC_n and the target fuel amount FCR_n (see FIG. 6) already calculated through the INNER-CYLINDER AIR AMOUNT ESTIMATION AND TARGET INNER-CYLINDER FUEL AMOUNT CALCULATION routine, the difference between the amount of fuel actually burnt within the cylinder and the target inner-cylinder fuel amount is derived as follows at step S120:

$$FD_0 \leftarrow MC_n / ABF - FCR_n$$

The reason for employing the values of the inner-cylinder air amount MC_n and the target inner-cylinder fuel amount FCR_n from n calls ago is that there is a lapse of time between the moment of detection of the A/F ratio by the A/F ratio sensor 45 and actual combustion. Such a time difference makes it necessary to store the values of the inner-cylinder air amount MC_i and the target inner-cylinder fuel amount FCR_i for the past n calls.

Next, at step S122, a fuel injection correction amount FT is derived by a proportional-integral control (hereinafter referred to as "PI control") as follows:

$$FT \leftarrow K_p \times FD_0 + K_s \times \sum FD_i$$

The first term on the right side of the equation is a proportional term of the PI control, where the coefficient K_p represents a gain for the proportional term. The second term on the right side of the equation is an integral term of the PI control, where the coefficient K_s represents a gain for the integral term.

FIG. 8 is a flow diagram illustrating the procedure of the FUEL INJECTION CONTROL routine, which is executed for every predetermined degrees of the crank angle. First, based on the target fuel amount FCR_n already calculated through the INNER-CYLINDER AIR AMOUNT ESTIMATION AND TARGET INNER-CYLINDER FUEL AMOUNT CALCULATION routine and on the fuel injection correction amount already calculated through the A/F RATIO FEEDBACK CONTROL routine, a fuel injection amount FI is derived as follows, at step S142:

$$FI \leftarrow FCR_0 \times \alpha + FT + \beta$$

α and β represent, respectively, a correction amount for a multiplicative correction coefficient and an additive correction amount. The values of α and β are determined by other parameters indicating the operation state. For example, α includes fundamental corrections based on the signals from sensors such as the air intake temperature sensor 43 and the water temperature sensor 44, whereas β includes a correction based on changes in the amount of fuel adhered on the walls of the cylinders, which may vary in accordance with the air intake tube pressure during a transition operation. Finally, the fuel injection amount FI thus obtained is set in the drive control circuit 77a for the fuel injection valve 60.

Although the above description is directed to a case where the feedback control is performed based on the output from the A/F ratio sensor 45 provided upstream of the catalyst, it is also possible to perform a secondary A/F ratio feedback control based on the output from the O_2 sensor 46 provided downstream of the catalyst. In that case, the output voltage VAF of the A/F ratio sensor upstream of the catalyst can be corrected based on the output from the O_2 sensor 46 downstream of the catalyst as follows:

$$VAF \leftarrow VAF + DV$$

In this case, an integration value is to be derived from the value of VAF corrected as above.

Now, the principles of the device according to the present invention for determining the deterioration of an A/F ratio sensor which is employed in an A/F ratio feedback control system for controlling the A/F ratio to a desired value by correcting the fuel injection amount based on a difference between the output from the A/F ratio sensor and the target A/F ratio will be described.

FIGS. 9A and 9B are graphs schematically illustrating the relationship between an output voltage VAF of an A/F ratio

sensor (solid line) and an ideal output voltage of the A/F ratio sensor reflecting the actual A/F ratio (broken line). FIG. 9A illustrates an A/F ratio sensor with normal response characteristics (defined herein as “high-response characteristics”), whose output VAF is substantially a voltage that ideally reflects the actual A/F ratio. FIG. 9B illustrates an A/F ratio sensor with deteriorated response characteristics (defined herein as “low-response characteristics”), whose output VAF poorly follows the voltage ideally reflecting the actual A/F ratio. As exemplified in FIG. 9B, the phase of the output VAF of the low-response A/F ratio sensor may lag behind the phase of the out-put VAF of the high-response A/F ratio sensor. In FIG. 9A, the offset of the output VAF of the high-response A/F ratio sensor from the target voltage (stoichiometric voltage) VAFT is expressed as an amplitude VP.

The A/F ratio feedback control is performed so that the fuel injection correction amount is increased as the offset of the output voltage VAF from the target voltage VAFT, corresponding to the stoichiometric A/F ratio (i.e., the amplitude VP of VAF with respect to VAFT) increases. For example, a fundamental fuel amount may be calculated by correcting (based on air intake temperature, etc.) a target inner-cylinder fuel amount VCR₀, which is calculated based on the inner-cylinder air amount MC₀ and the stoichiometric A/F ratio AFT. Then, an A/F ratio of the actual exhaust gas, as measured by the A/F ratio sensor 45, can be compared against this fundamental fuel amount, whereby a feedback correction which is in accordance with the offset from the stoichiometric A/F ratio can be made.

FIGS. 10A and 10B illustrate an exemplary feedback correction to be performed for the fuel injection amount. FIG. 10A illustrates the output VAF of a high-response A/F ratio sensor (broken line) and the output VAF of a low-response A/F ratio sensor (solid line) against time (the axis of abscissas). The fuel injection correction amount FT or FT' shown in FIG. 10B corresponds to the feedback correction for the fundamental injection amount as mentioned above As shown in FIG. 10B, the high-response A/F ratio sensor can provide a feedback correction (FT) based on the output VAF which accurately reflects the voltage corresponding to the actual A/F ratio On the other hand, the low-response A/F ratio sensor provides a feedback correction (FT') based on its deteriorated characteristics, e.g., the output VAF' whose phase lags behind the voltage corresponding to the actual A/F ratio.

As shown in FIG. 10A, the feedback control starting from time t₀ typically proceeds as follows: The output VAF of the high-response A/F ratio sensor, which accurately reflects the voltage corresponding, to the actual A/F ratio, gradually increases from the rich side (with its amplitude gradually decreasing), exceeds the stoichiometric A/F ratio VAFT (with its amplitude being zero), continues increasing on the lean side (with its amplitude increasing), and again decreases past time t₁ (with its amplitude decreasing) The fuel injection correction amount FT, as shown in FIG. 10B, keeps decreasing correspondingly, reaches a predetermined correction amount at t₁, and then increases again.

In contrast, the output VAF' of the low-response A/F ratio sensor, due to its slow response, is still monotonously increasing (with its amplitude decreasing) even after the output of the high-response A/F ratio sensor has shifted from the rich side to the lean side across the stoichiometric A/F ratio VAFT between time t₀ and time t₁ in FIG. 10A. Therefore, as shown in FIG. 10B, the fuel injection correction amount FT' continues decreasing past the appropriate correction level although it should already be increasing

(which would be the case if the response characteristics of the A/F ratio sensor had not deteriorated, i.e., reflecting the voltage corresponding to the actual A/F ratio) Thus, in the A/F ratio control system described above, once the response characteristics of the A/F ratio sensor have deteriorated from the proper sensor response characteristics intended for the feedback system, an excessive correction may be performed for the fundamental injection amount. For example, as shown in FIG. 10B, the fuel injection correction amount of the low-response A/F ratio sensor between time t₀ and time t₁ varies by an amount $\Delta FT'$, which is substantially larger than the amount ΔFT by which the fuel injection correction amount of the high-response A/F ratio sensor varies during the same period.

As a result, the feedback control with the low-response A/F ratio sensor provides poor convergence to the target A/F ratio value, so that the A/F ratio bounces between excessively rich states and excessively lean states across the target A/F ratio, with the output VAF of the A/F ratio sensor and the fuel injection correction amount per unit time (or a predetermined time interval) greatly varying. By paying attention to this relatively large variation, the present invention provides an accurate detection of the deterioration of the A/F ratio sensor. Specifically, the present invention utilizes, for example, a cumulative value of the variation in the output of the A/F ratio sensor or the fuel injection correction amount taken over a predetermined period of time; the A/F ratio sensor is determined as deteriorated when the cumulative value exceeds a predetermined value.

In the following description, the fuel injection correction amount will be represented in terms of a fuel injection correction rate (hereinafter referred to as “FIC rate (%))” representing the rate of correction amount relative to the fundamental injection amount, as illustrated in FIGS. 11A and 11B. FIG. 11A shows the output of an exemplary A/F ratio sensor, and FIG. 11B shows the corresponding FIC rate (%) according to the above-described feedback control. As explained above, a cumulative (or summation) value $S_1 = \sum \Delta FT_m$, which is obtained by calculating the variation ΔFT_m in the FIC rate FT at a predetermined time interval and summing all the variation ΔFT_m , becomes larger for a low-response A/F ratio sensor than for a normal or high-response A/F ratio sensor. The variation ΔFT_1 and ΔFT_2 shown in FIG. 11B are obtained at a time interval of 65 ms.

Alternatively, either one of the followings can be adopted as an index of deterioration in the response characteristics of an A/F ratio sensor: a cumulative value which is obtained by calculating the offset of the output of the A/F ratio sensor from a target output corresponding to the target A/F ratio at a predetermined time interval and summing all the offsets; and a cumulative value which is obtained by calculating the variation in the output of the A/F ratio sensor at a predetermined time interval and summing all the variation. For example, as shown in FIG. 11A, a cumulative value $S_2 = \sum V_m$, which is obtained by calculating the offset V_m (m=1, 2, . . .) of the output of the A/F ratio sensor from a target output VAFT corresponding to the stoichiometric A/F ratio at a predetermined time interval and summing all the off-sets V_m , or a cumulative value $S_3 = \sum \Delta V_m$, which is obtained by calculating the variation ΔV_m in the output of the A/F ratio sensor at a predetermined time interval and summing all the variation ΔV_m , similarly becomes larger for a low-response A/F ratio sensor than for a normal or high-response A/F ratio sensor. Accordingly, an A/F ratio sensor can be determined as deteriorated when any of these cumulative values exceeds a predetermined value, thereby providing an accurate detection of malfunctioning of the A/F ratio sensor.

Alternatively, the following can be adopted as an index of deterioration in the response characteristics of an A/F ratio sensor: Since deterioration in the response characteristics of an A/F ratio sensor causes a decrease in its ability to follow a value obtained by dividing the variation in the FIC rate during a predetermined period by the variation in the output of the A/F ratio sensor during the same period increases as the response characteristics of the A/F ratio sensor deteriorate. For example, as shown in FIG. 10A, the variation $\Delta V'$ of the low-response A/F ratio sensor between time t_0 and time t_1 is smaller than the variation ΔV of the high-response A/F ratio sensor during the same period. Therefore, a value P' obtained by dividing the cumulative value $\Sigma\DeltaFT'$ of the variation $\DeltaFT'$ in the FIC rate of the low-response A/F ratio sensor between time t_0 and time t_1 (described above with reference to FIG. 10B) by a cumulative value $\Sigma\DeltaV'$ of the corresponding variation $\DeltaV'$ in the low-response A/F ratio sensor output becomes larger than a value P obtained by dividing the cumulative value $\Sigma\DeltaFT$ of the variation ΔFT in the FIC rate FT of the high-response A/F ratio sensor between time t_0 and time t_1 by a cumulative value $\Sigma\DeltaV$ (i.e., S_3) of the corresponding variation ΔV in the high-response A/F ratio sensor output. FIG. 12 schematically shows the relationship between the response characteristics of an A/F ratio sensor and a value $P=\Sigma\DeltaFT/\Sigma\DeltaV$ (or $P'=\Sigma\DeltaFT'/\Sigma\DeltaV'$). Accordingly, an A/F ratio sensor is determined as deteriorated when the value $P=\Sigma\DeltaFT/\Sigma\DeltaV$ ($=S_1/S_3$) exceeds a predetermined value, thereby providing an accurate detection of the malfunctioning of the A/F ratio sensor.

Alternatively, paying attention to the geometrical characteristics of the output waveform of an A/F ratio sensor, an index of deterioration in the response characteristics of an A/F ratio sensor can be derived from a cumulative value of the A/F ratio sensor output and a cumulative value of the variation in the A/F ratio sensor output. As shown in FIGS. 13A and 13B, the cumulative value $S_3=\Sigma\DeltaV_n$ of the variation in the output of the A/F ratio sensor is in proportion with both the frequency of variation and the output amplitude of the output of the A/F ratio sensor. On the other hand, the cumulative value $S_2=\Sigma V_m$ of the offset of the output of the A/F ratio sensor from a target output corresponding to the stoichiometric A/F ratio is substantially in proportion with the output amplitude but relatively independent from the frequency of variation. Therefore, a value Q which is obtained by dividing the cumulative value $S_2=\Sigma V_m$ of the offset of the output of the A/F ratio sensor from the target output corresponding to the stoichiometric A/F ratio by the cumulative value S_3 of the variation in the output of the A/F ratio sensor (i.e., $Q=S_2/S_3=\Sigma V_m/\Sigma\DeltaV_n$) is in inverse proportion with the variation frequency of the output of the A/F ratio sensor, with the influence of the amplitude of the A/F ratio sensor output being removed. That is, the value $Q=\Sigma V_m/\Sigma\DeltaV_n$ is in proportion with the variation cycle T (or T').

As seen from FIGS. 13A and 13B, the variation cycle T (or T') of the output of the A/F ratio sensor depends on the response characteristics of the A/F ratio sensor. Therefore, the value $Q=\Sigma V_m/\Sigma\DeltaV_n$, i.e., the ratio of the cumulative output of an A/F ratio sensor and cumulative variation in the output of the A/F ratio sensor increases as the response characteristics of the A/F ratio sensor deteriorate. This relationship is schematically shown in FIG. 14. Accordingly, an A/F ratio sensor is determined as deteriorated when the value $Q=\Sigma V_m/\Sigma\DeltaV_n$ exceeds a predetermined value, thereby providing an accurate detection of the malfunctioning of the A/F ratio sensor.

The above-described indices P and Q are each correlated with the response characteristics of an A/F ratio sensor.

Therefore, a value R which is obtained by multiplying P by Q (expressed in equation (1) below) is even more clearly correlated with the response characteristics of an A/F ratio sensor.

$$R = PQ = (\Sigma\DeltaFT_m / \Sigma\DeltaV_n) \cdot (\Sigma V_m / \Sigma\DeltaV_n) = (\Sigma\DeltaFT_m \cdot \Sigma V_m) / (\Sigma\DeltaV_n)^2 \quad \text{eq.(1)}$$

Accordingly, an A/F ratio sensor can be determined as deteriorated when the value R exceeds a predetermined value, thereby providing an accurate detection of the malfunctioning of the A/F ratio sensor.

Thus, the deterioration of an A/F ratio sensor can be detected by utilizing one or any combination of the above-mentioned indices. Furthermore, it becomes possible to detect the early deterioration in the A/F ratio controllability due to the deteriorated characteristics of the A/F ratio sensor output and to prevent consequent aggravation of the exhaust emissions.

In the Examples given below, each procedure for determining the deterioration in the response characteristics of the output of an A/F ratio sensor, based on the above-described indices S_1 , S_2 , S_3 , P , Q , and/or R , will be described with reference to a corresponding flow diagram. The procedure in each Example is performed by the use of the CPU 71 (FIG. 4) included in the engine ECU 70 (FIG. 3). As already described with reference to FIG. 4, the system and its respective component elements as well as various sensors are coupled (via the A/D convertor circuit 75 or the input interface circuit 76) to the CPU 71, where the following procedure and determination are performed based on the signals which are provided from such elements. The various data and measurement values required for the procedure are stored in the RAM 74 for use. The A/F ratio sensor OUTPUT DETERIORATION (MALFUNCTIONING) DETERMINATION routine in each Example is performed in accordance with a predetermined clock so as to be repeated at a predetermined cycle.

EXAMPLE 1

As Example 1 of the present invention, a procedure for determining the deterioration in the response characteristics of an A/F ratio sensor based on the cumulative value S_1 (i.e., $\Sigma\DeltaFT$) of the variation ΔFT in the FIC rate will be described with reference to a flow diagram of FIG. 15 showing the A/F ratio sensor OUTPUT DETERIORATION (MALFUNCTIONING) DETERMINATION routine according to Example 1.

As shown in FIG. 15, at step S201, it is determined whether or not the conditions are satisfied for permitting the execution of the process for detecting the malfunctioning of the A/F ratio sensor (hereinafter such conditions are referred to as "detection-permitting conditions"). The detection-permitting conditions may include, for example, that the travel speed of the automobile is within a predetermined range; that the rotation rate of the engine is within a predetermined range; that a feedback control is ongoing; and that other components and the system are free from malfunctions which may cause misdetections. Such detection-permitting conditions are checked by detecting the input signals from various sensors. If the detection-permitting conditions are satisfied, the control proceeds to the next step S202. If the detection-permitting conditions are not satisfied, the cumulative value S_1 ($=\Sigma\DeltaFT$) up to the previous call of the routine is cleared at step S210 and thereafter the control exits the routine.

The detection-permitting conditions must be satisfied in order to ensure that only accurate FIC rate values are used for the calculation of the variation ΔFT in the FIC rate at each time interval T_1 .

The variation ΔFT in the FIC rate is calculated at every predetermined time interval T_1 . The time interval T_1 is required to be sufficiently short relative to the variation cycle of A/F ratio sensor output so that an accurate cumulative value $\Sigma\Delta FT$ of the variation ΔFT in the FIC rate is obtained. At step S202, it is determined whether or not the routine cycle (as determined by a predetermined clock) is at a point where it coincides with a cycle defined by the time interval T_1 for calculating the variation ΔFT in the FIC rate. If it is determined that the routine cycle does not coincide with the cycle defined by the time interval T_1 , the control exits the routine without performing any processes. If it is determined that the routine cycle coincides with the cycle defined by the time interval T_1 , the control proceeds to the next step S203.

The cycle of the malfunctioning detection routine must be prescribed as equal to or smaller than the time interval T_1 for calculating the variation ΔFT in the FIC rate. Step S202 can be omitted in the case where the cycle of the malfunctioning detection routine is prescribed as equal to the time interval T_1 for calculating the variation ΔFT in the FIC rate.

At step S203, it is determined whether or not T_2 seconds have passed since the detection-permitting conditions were confirmed to be satisfied at step S201. The reasons for performing the determination of step S203 are as follows: As described above, the detection-permitting conditions of step S201 must be satisfied in order to ensure that only accurate FIC rate values are used for the calculation of the variation ΔFT in the FIC rate at every time interval T_1 . In order to prevent the cumulation process from being influenced by a previous state where the detection-permitting conditions were not satisfied, it is preferable to wait T_2 seconds after the detection-permitting conditions were satisfied before the variation ΔFT in the FIC rate is added to the cumulative value $\Sigma\Delta FT$ (i.e., S_1). Thus, the accuracy of the cumulative data of the variation ΔFT in the FIC rate is ensured. Preferably, T_1 and T_2 satisfy the relationship $T_1 \leq T_2$. If it is determined at step S203 that T_2 seconds have not passed after the affirmation of the detection-permitting conditions, step S209 is performed to store the current FIC rate FT, and thereafter the control exits the routine. If it is determined at step S203 that T_2 seconds have passed after the affirmation of the detection-permitting conditions, then the control proceeds to the next step S204.

At step S204, the absolute value of a difference between the current FIC rate (FT_m) and the FIC rate (FT_{m-1}) previously stored at step S209 in a previous call of the routine (i.e., $\Delta FT_m = |FT_m - FT_{m-1}|$) is calculated, and the difference (or "variation") ΔFT_m is added to the cumulative value obtained up to the previous call of the routine (i.e., $\Sigma\Delta FT_{m-1}$), thereby updating the cumulative value $\Sigma\Delta FT$. When step S204 is performed for the first time after the conditions of steps S201 to S203 are satisfied, an initial value (=0) is substituted for the cumulative value ($\Sigma\Delta FT_{m-1}$) obtained up to the previous call of the routine (the initial value is used when the detection-permitting conditions are not satisfied at step S201).

Step S205 counts the number of times the cumulation process has been performed at step S204. If the cumulation process has been performed m times, it is known that the cumulation of the variation ΔFT in the FIC rate has been performed for $T_s = m \times T_1$ (defined as "hitherto-performed cumulation time") in total. Assuming that the cumulation

process is to be performed a total of M times (as counted at step S206 described later), the process of cumulating the variation ΔFT in the FIC rate must be performed for a predetermined time duration of $T_\Sigma = M \times T_1$ (defined as the "cumulation time"). Alternatively, it is possible to control the predetermined time duration (cumulation time) by measuring the duration T_{cont} of cumulation continued after the condition of step S203 is satisfied (i.e., T_2 seconds or more have passed).

The value of M representing the number of times the cumulation process is to be performed (or the cumulation time T_Σ), or the duration T_Σ' of cumulation to be continued after the condition of step S203 is satisfied, is prescribed so that the cumulation process will be performed for a period of time sufficiently longer than the variation cycle of the FIC rate due to the feedback correction.

At step S206, it is determined whether or not the value of m (i.e., the number of times the cumulation process has been hitherto performed), as counted at step S205, is equal to or greater than the above-mentioned predetermined value M (i.e., the total number of times the cumulation process is to be performed). Alternatively, in the case where the cumulation time T_Σ is controlled by measuring the duration T_{cont} of cumulation after the condition of step S203 is satisfied, it is determined at step S206 whether or not the duration T_{cont} of cumulation after the condition of step S203 is satisfied is equal to or greater than the duration T_Σ' of cumulation to be continued after the condition of step S203 is satisfied.

It should be noted that the cumulation time T_Σ , during which the variation in the FIC rate is cumulated, need not be one continuous stretch of time. For example, if any of the detection-permitting conditions at step S201 is not satisfied before the hitherto-performed cumulation time T_s reaches the predetermined value T_Σ , the cumulative value S_1 (i.e., $\Sigma\Delta FT$) of the variation ΔFT in FIC rate FT, the cumulation time T_s (defined in terms of m , i.e., a number of times the cumulation process has been performed, or in terms of T_{cont} , i.e., a duration of cumulation after the condition of step S203 is satisfied) and the like can be stored without being cleared, so that these values can be utilized when the process is resumed after the conditions of steps S201 to S203 are again satisfied, and the cumulation process of the variation ΔFT in the FIC rate FT as well as the counting of the number m or the duration T_{cont} of cumulation can be continued after the condition of step S203 is satisfied. Such resumption and continuation of the process will be described later in more detail. If the condition of step S206 is satisfied (i.e., if the cumulation process has been performed for the predetermined cumulation time T_Σ), then the control proceeds to step S207. If the condition of step S206 is not satisfied, only step S209 (i.e., storing the current FIC rate FT) is performed and thereafter the control exits the routine.

At step S207, it is determined whether or not the cumulative value $\Sigma\Delta FT$ (i.e., S_1) of the variation ΔFT in the FIC rate FT exceeds a predetermined threshold value $\Sigma\Delta FT(th)$. If the cumulative value $\Sigma\Delta FT$ does not exceed the threshold value $\Sigma\Delta FT(th)$, the A/F ratio sensor is determined as having normal characteristics (step S208b). If the cumulative value $\Sigma\Delta FT$ exceeds the threshold value $\Sigma\Delta FT(th)$, the A/F ratio sensor is determined as malfunctioning or having deteriorated characteristics (step S208a). When the A/F ratio sensor is determined as malfunctioning, a malfunction alert indicator within an instrument panel may be lit, for example.

EXAMPLE 2

As Example 2 of the present invention, a procedure for determining the deterioration in the response characteristics

of an A/F ratio sensor based on the cumulative value S_2 (i.e., ΣV) of the offset (i.e., the absolute value V of the A/F ratio sensor output) between the output of the A/F ratio sensor and a target output corresponding to the stoichiometric A/F ratio will be described with reference to a flow diagram of FIG. 16 showing the A/F ratio sensor OUTPUT DETERIORATION (MALFUNCTIONING) DETERMINATION routine according to Example 2.

As shown in FIG. 16, at step S301, it is determined whether or not the conditions are satisfied for permitting the execution of the process for detecting the malfunctioning of the A/F ratio sensor (“detection-permitting conditions”) The detection-permitting conditions may include, for example, that the travel speed of the automobile is within a predetermined range; that the rotation rate of the engine is within a predetermined range; that a feedback control is ongoing; and that other components and the system are free from malfunctions which may cause mis detections. Such detection-permitting conditions are checked by detecting the input signals from various sensors. If the detection-permitting conditions are satisfied, the control proceeds to the next step S302. If the detection-permitting conditions are not satisfied, the cumulative value S_1 ($=\Sigma V$) up to the previous call of the routine is cleared at step S310 and thereafter the control exits the routine.

The detection-permitting conditions must be satisfied in order to ensure that only accurate values of the A/F ratio sensor output are used for the calculation at each time interval T_1 .

The absolute value V of the A/F ratio sensor output is calculated at every predetermined time interval T_1 . The time interval T_1 is required to be sufficiently short relative to the variation cycle of A/F ratio sensor output so that an accurate cumulative value ΣV of the absolute value V of the A/F ratio sensor output is obtained. At step S302, it is determined whether or not the routine cycle (as determined by a predetermined clock) is at a point where it coincides with a cycle defined by the time interval T_1 for calculating the absolute value V of the A/F ratio sensor output. If it is determined that the routine cycle does not coincide with the cycle defined by the time interval T_1 , the control exits the routine without performing any processes. If it is determined that the routine cycle coincides with the cycle defined by the time interval T_1 , the control proceeds to the next step S303.

The cycle of the malfunctioning detection routine must be prescribed as equal to or smaller than the time interval T_1 for calculating the absolute value V of the A/F ratio sensor output. Step S302 can be omitted in the case where the cycle of the malfunctioning detection routine is prescribed as equal to the time interval T_1 for calculating the absolute value V of the A/F ratio sensor output.

At step S303, it is determined whether or not T_2 seconds have passed since the detection-permitting conditions were confirmed to be satisfied at step S301. The reasons for performing the determination of step S303 are as follows: As described above, the detection-permitting conditions of step S301 must be satisfied in order to ensure that only accurate absolute values V of the A/F ratio sensor output are used for the calculation at every time interval T_1 . In order to prevent the cumulation process from being influenced by the inaccuracy emanating from a previous state where the detection-permitting conditions were not satisfied, it is preferable to wait T_2 seconds after the detection-permitting conditions were satisfied before the absolute value V of the A/F ratio sensor output is added to the cumulative value ΣV (i.e., S_2). Thus, the accuracy of the cumulative data of the absolute

value V of the A/F ratio sensor output is ensured. Preferably, T_1 and T_2 satisfy the relationship $T_1 \leq T_2$. If it is determined at step S303 that T_2 seconds have not passed after the affirmation of the detection-permitting conditions, the control exits the routine. If it is determined at step S303 that T_2 seconds have passed after the affirmation of the detection-permitting conditions, then the control proceeds to the next step S304.

At step S304, the absolute value V of the A/F ratio sensor output is calculated and added to the cumulative value obtained up to the previous call of the routine (i.e., ΣV_{m-1}), thereby updating the cumulative value ΣV . In the case where the A/F ratio sensor output corresponding to the stoichiometric A/F ratio is not zero, e.g., if the A/F ratio sensor output corresponding to the stoichiometric A/F ratio is designed to have a certain offset value, the offset value is eliminated before the cumulation calculation. If the control target of the A/F ratio is not the stoichiometric A/F ratio, the cumulation calculation can be directed to the cumulation of the absolute values of offsets from the target A/F ratio. When step S304 is performed for the first time after the conditions of steps S301 to S303 are satisfied, an initial value (=0) is substituted for the cumulative value (ΣV_{m-1}) obtained up to the previous call of the routine (the initial value is used when the detection-permitting conditions are not satisfied at step S301).

Step S305 counts the number of times the cumulation process has been performed at step S304. If the cumulation process has been performed m times, it is known that the cumulation of the absolute value V of the A/F ratio sensor output has been performed for $T_s = m \times T_1$ (defined as “hitherto-performed cumulation time”) in total. Assuming that the cumulation process is to be performed a total of M times (as counted at step S306 described later), the process of cumulating the absolute value V of the A/F ratio sensor output must be performed for a predetermined time duration of $T_{\Sigma} = M \times T_1$ (defined as the “cumulation time”). Alternatively, it is possible to control the predetermined time duration (cumulation time) by measuring the duration T_{Σ}^{cont} of cumulation continued after the condition of step S303 is satisfied (i.e., T_2 seconds or more have passed).

The value of M representing the number of times the cumulation process is to be performed (or the cumulation time T_{Σ}), or the duration T_{Σ}^{cont} of cumulation to be continued after the condition of step S303 is satisfied, is prescribed so that the cumulation process will be performed for a period of time sufficiently longer than the variation cycle of the A/F ratio sensor output due to the feedback correction.

At step S306, it is determined whether or not the value of m (i.e., the number of times the cumulation process has been hitherto performed), as counted at step S305, is equal to or greater than the above-mentioned predetermined value M (i.e., the total number of times the cumulation process is to be performed). Alternatively, in the case where the cumulation time T_{Σ} is controlled by measuring the duration T_{Σ}^{cont} of cumulation after the condition of step S303 is satisfied, it is determined at step S306 whether or not the duration T_{Σ}^{cont} of cumulation after the condition of step S303 is satisfied is equal to or greater than the duration T_{Σ}^{cont} of cumulation to be continued after the condition of step S303 is satisfied.

It should be noted that the cumulation time T_{Σ} , during which the absolute value V of the A/F ratio sensor output is cumulated, need not be one continuous stretch of time. For example, if any of the detection-permitting conditions at step S301 is not satisfied before the hitherto-performed cumulation time T_s reaches the predetermined value T_{Σ} , the

cumulative value S_2 (i.e., ΣV) of the absolute value V of the A/F ratio sensor output, the cumulation time T_s (defined in terms of m , i.e., a number of times the cumulation process has been performed, or in terms of T_{cont} , i.e., a duration of cumulation after the condition of step S303 is satisfied) and the like can be stored without being cleared, so that these values can be utilized when the process is resumed after the conditions of steps S301 to S303 are again satisfied, and the cumulation process of the absolute value V of the A/F ratio sensor output as well as the counting of the number m or the duration T_{cont} of cumulation can be continued after the condition of step S303 is satisfied. Such resumption and continuation of the process will be described later in more detail. If the condition of step S306 is satisfied (i.e., if the cumulation process has been performed for the predetermined cumulation time T_s), then the control proceeds to step S307. If the condition of step S306 is not satisfied, the control exits the routine.

At step S307, it is determined whether or not the cumulative value ΣV (i.e., S_2) of the absolute value V of the A/F ratio sensor output exceeds a predetermined threshold value $\Sigma V(th)$. If the cumulative value ΣV does not exceed the threshold value $\Sigma V(th)$, the A/F ratio sensor is determined as having normal characteristics (step S308b). If the cumulative value ΣV exceeds the threshold value $\Sigma V(th)$, the A/F ratio sensor is determined as malfunctioning or having deteriorated characteristics (step S308a). When the A/F ratio sensor is determined as malfunctioning, a malfunction alert indicator within an instrument panel may be lit, for example.

In the present example, it is unnecessary to store the current A/F ratio sensor output before exiting the routine as in the other Examples because it is not necessary to calculate a difference ΔV from the A/F ratio sensor output from T_1 seconds ago, or a difference ΔFT from the FIC rate from T_1 seconds ago.

EXAMPLE 3

As Example 3 of the present invention, a procedure for determining the deterioration in the response characteristics of an A/F ratio sensor based on the cumulative value S_3 (i.e., $\Sigma \Delta V$) of the variation in the A/F ratio sensor output will be described with reference to a flow diagram of FIG. 17 showing the A/F ratio sensor OUTPUT DETERIORATION (MALFUNCTIONING) DETERMINATION routine according to Example 3.

As shown in FIG. 17, at step S401, it is determined whether or not the conditions are satisfied for permitting the execution of the process for detecting the malfunctioning of the A/F ratio sensor ("detection-permitting conditions"). The detection-permitting conditions may include, for example, that the travel speed of the automobile is within a predetermined range; that the rotation rate of the engine is within a predetermined range; that a feedback control is ongoing; and that other components and the system are free from malfunctions which may cause mis detections. Such detection-permitting conditions are checked by detecting the input signals from various sensors. If the detection-permitting conditions are satisfied, the control proceeds to the next step S402. If the detection-permitting conditions are not satisfied, the cumulative value S_3 ($=\Sigma \Delta V$) up to the previous call of the routine is cleared at step S410 and thereafter the control exits the routine.

The detection-permitting conditions must be satisfied in order to ensure that only accurate values of the variation ΔV in the A/F ratio sensor output are used for the calculation at each time interval T_1 .

The variation ΔV in the A/F ratio sensor output is calculated at every predetermined time interval T_1 . The time interval T_1 is required to be sufficiently short relative to the variation cycle of A/F ratio sensor output so that an accurate cumulative value $\Sigma \Delta V$ of the variation ΔV in the A/F ratio sensor output is obtained. At step S402, it is determined whether or not the routine cycle (i.e., as determined by a predetermined clock) is at a point where it coincides with a cycle defined by the time interval T_1 for calculating the variation ΔV in the A/F ratio sensor output. If it is determined that the routine cycle does not coincide with the cycle defined by the time interval T_1 , the control exits the routine without performing any processes. If it is determined that the routine cycle coincides with the cycle defined by the time interval T_1 , the control proceeds to the next step S403.

The cycle of the malfunctioning detection routine must be prescribed as equal to or smaller than the time interval T_1 for calculating the variation ΔV in the A/F ratio sensor output. Step S402 can be omitted in the case where the cycle of the malfunctioning detection routine is prescribed as equal to the time interval T_1 for calculating the variation ΔV in the A/F ratio sensor output.

At step S403, it is determined whether or not T_2 seconds have passed since the detection-permitting conditions were confirmed to be satisfied at step S401. The reasons for performing the determination of step S403 are as follows: As described above, the detection-permitting conditions of step S401 must be satisfied in order to ensure that only accurate values of variation ΔV in the A/F ratio sensor output are used for the calculation at every time interval T_1 . In order to prevent the cumulation process from being influenced by a previous state where the detection-permitting conditions were not satisfied, it is preferable to wait T_2 seconds after the detection-permitting conditions were satisfied before the variation ΔV in the A/F ratio sensor output is added to the cumulative value $\Sigma \Delta V$ (i.e., S_3). Thus, the accuracy of the cumulative data of the variation ΔV in the A/F ratio sensor output is ensured. Preferably, T_1 and T_2 satisfy the relationship $T_1 \leq T_2$. If it is determined at step S403 that T_2 seconds have not passed after the affirmation of the detection-permitting conditions, step S409 is performed to store the current A/F ratio sensor output and thereafter the control exits the routine. If it is determined at step S403 that T_2 seconds have passed after the affirmation of the detection-permitting conditions, then the control proceeds to the next step S404.

At step S404, the absolute value of a difference between the current A/F ratio sensor output (V_m) and the A/F ratio sensor output (V_{m-1}) previously stored at step S409 in a previous call of the routine (i.e., $\Delta V_m = |V_m - V_{m-1}|$) is calculated, and the difference (or "variation") ΔV_m is added to the cumulative value obtained up to the previous call of the routine (i.e., $\Sigma \Delta V_{m-1}$), thereby updating the cumulative value $\Sigma \Delta V$. When step S404 is performed for the first time after the conditions of steps S401 to S403 are satisfied, an initial value ($=0$) is substituted for the cumulative value ($\Sigma \Delta V_{m-1}$) obtained up to the previous call of the routine (the initial value is used when the detection-permitting conditions are not satisfied at step S401).

Step S405 counts the number of times the cumulation process has been performed at step S404. If the cumulation process has been performed m times, it is known that the cumulation of the variation ΔV in the A/F ratio sensor output has been performed for $T_s = m \times T_1$ (defined as "hitherto-performed cumulation time") in total. Assuming that the cumulation process is to be performed a total of M times (as counted at step S406 described later), the process of cumu-

lating the variation ΔV in the A/F ratio sensor output must be performed for a predetermined time duration of $T_{\Sigma} = M \times T_1$ (defined as the “cumulation time”). Alternatively, it is possible to control the predetermined time duration (cumulation time) by measuring the duration T_{cont} of cumulation continued after the condition of step S403 is satisfied (i.e., T_2 seconds or more have passed).

The value of M representing the number of times the cumulation process is to be performed (or the cumulation time T_{Σ}), or the duration T_{Σ}' of cumulation to be continued after the condition of step S403 is satisfied, is prescribed so that the cumulation process will be performed for a period of time sufficiently longer than the variation cycle of the variation ΔV in the A/F ratio sensor output due to the feedback correction.

At step S406, it is determined whether or not the value of m (i.e., the number of times the cumulation process has been hitherto performed), as counted at step S405, is equal to or greater than the above-mentioned predetermined value M (i.e., the total number of times the cumulation process is to be performed). Alternatively, in the case where the cumulation time T_{Σ} is controlled by measuring the duration T_{cont} of cumulation after the condition of step S403 is satisfied, it is determined at step S406 whether or not the duration T_{cont} of cumulation after the condition of step S403 is satisfied is equal to or greater than the duration T_{Σ}' of cumulation to be continued after the condition of step S403 is satisfied.

It should be noted that the cumulation time T_{Σ} , during which the variation ΔV in the A/F ratio sensor output is cumulated, need not be one continuous stretch of time. For example, if any of the detection-permitting conditions at step S401 is not satisfied before the hitherto-performed cumulation time T_s reaches the predetermined value T_{Σ} , the cumulative value S_3 (i.e., $\Sigma\Delta V$) of the variation ΔV in the A/F ratio sensor output, the cumulation time T_s (defined in terms of m , i.e., a number of times the cumulation process has been performed, or in terms of T_{cont} , i.e., a duration of cumulation after the condition of step S403 is satisfied) and the like can be stored without being cleared, so that these values can be utilized when the process is resumed after the conditions of steps S401 to S403 are again satisfied, and the cumulation process of the variation ΔV in the A/F ratio sensor output as well as the counting of the number m or the duration T_{cont} of cumulation can be continued after the condition of step S403 is satisfied. Such resumption and continuation of the process will be described later in more detail. If the condition of step S406 is satisfied (i.e., if the cumulation process has been performed for the predetermined cumulation time T_{Σ}), then the control proceeds to step S407. If the condition of step S406 is not satisfied, only step S409 (i.e., storing the current A/F ratio sensor output) is performed and thereafter the control exits the routine.

At step S407, it is determined whether or not the cumulative value $\Sigma\Delta V$ (i.e., S_3) of the variation ΔV in the A/F ratio sensor output exceeds a predetermined threshold value $\Sigma\Delta V(\text{th})$. If the cumulative value $\Sigma\Delta V$ does not exceed the threshold value $\Sigma\Delta V(\text{th})$, the A/F ratio sensor is determined as having normal characteristics (step S408b). If the cumulative value $\Sigma\Delta V$ exceeds the threshold value $\Sigma\Delta V(\text{th})$, the A/F ratio sensor is determined as malfunctioning or having deteriorated characteristics (step S408a). When the A/F ratio sensor is determined as malfunctioning, a malfunction alert indicator within an instrument panel may be lit, for example.

EXAMPLE 4

As Example 4 of the present invention, a procedure for determining the deterioration in the response characteristics

of an A/F ratio sensor based on the cumulative value S_1 (i.e., $\Sigma\Delta F$) of the variation ΔF in the FIC rate and the cumulative value S_3 (i.e., $\Sigma\Delta V$) of the variation ΔV in the A/F ratio sensor output will be described with reference to a flow diagram of FIG. 18 showing the A/F ratio sensor OUTPUT DETERIORATION (MALFUNCTIONING) DETERMINATION routine according to Example 4.

As shown in FIG. 18, at step S501, it is determined whether or not the conditions are satisfied for permitting the execution of the process for detecting the malfunctioning of the A/F ratio sensor (“detection-permitting conditions”). The detection-permitting conditions may include, for example, that the travel speed of the automobile is within a predetermined range; that the rotation rate of the engine is within a predetermined range; that a feedback control is ongoing; and that other components and the system are free from malfunctions which may cause mis detections. Such detection-permitting conditions are checked by detecting the input signals from various sensors. If the detection-permitting conditions are satisfied, the control proceeds to the next step S502. If the detection-permitting conditions are not satisfied, the cumulative value S_1 ($=\Sigma\Delta F$) and S_3 ($=\Sigma\Delta V$) up to the previous call of the routine is cleared at step S513 and thereafter the control exits the routine.

The detection-permitting conditions must be satisfied in order to ensure that only accurate FIC rate values and accurate A/F ratio sensor output values are used for the calculation at each time interval T_1 .

The variation ΔF in the FIC rate and the variation ΔV in the A/F ratio sensor output are calculated at every predetermined time interval T_1 . The time interval T_1 is required to be sufficiently short relative to the variation cycle of A/F ratio sensor output so that an accurate cumulative value $\Sigma\Delta F$ of the variation ΔF in the FIC rate and an accurate cumulative value $\Sigma\Delta V$ of the variation ΔV in the A/F ratio sensor output are obtained. At step S502, it is determined whether or not the routine cycle (i.e., as determined by a predetermined clock) is at a point where it coincides with a cycle defined by the time interval T_1 for calculating the variation ΔF in the FIC rate and the variation ΔV in the A/F ratio sensor output. If it is determined that the routine cycle does not coincide with the cycle defined by the time interval T_1 , the control exits the routine without performing any processes. If it is determined that the routine cycle coincides with the cycle defined by the time interval T_1 , the control proceeds to the next step S503.

The cycle of the malfunctioning detection routine must be prescribed as equal to or smaller than the time interval T_1 for calculating the variation ΔF in the FIC rate and the variation ΔV in the A/F ratio sensor output. Step S502 can be omitted in the case where the cycle of the malfunctioning detection routine is prescribed as equal to the time interval T_1 for calculating the variation ΔF in the FIC rate and the variation ΔV in the A/F ratio sensor output.

At step S503, it is determined whether or not T_2 seconds have passed since the detection-permitting conditions were confirmed to be satisfied at step S501. The reasons for performing the determination of step S503 are as follows: As described above, the detection-permitting conditions of step S501 must be satisfied in order to ensure that only accurate FIC rate values and accurate values of A/F ratio sensor output are used for the respective calculation of the variation ΔF in the FIC rate and the variation ΔV in the A/F ratio sensor output at every time interval T_1 . In order to prevent the cumulation process from being influenced by a previous state where the detection-permitting conditions were not

satisfied, it is preferable to wait T_2 seconds after the detection-permitting conditions were satisfied before the variation ΔFT in the FIC rate is added to the cumulative value $\Sigma \Delta FT$ (i.e., S_1) and the variation ΔV in the A/F ratio sensor output is added to the cumulative value $\Sigma \Delta V$ (i.e., S_3). Thus, the accuracy of the cumulative data of the variation ΔFT in the FIC rate and the cumulative data of the variation ΔV in the A/F ratio sensor output is ensured. Preferably, T_1 and T_2 satisfy the relationship $T_1 \leq T_2$. If it is determined at step S503 that T_2 seconds have not passed after the affirmation of the detection-permitting conditions, step S511 is performed to store the current FIC rate FT and step S512 is performed to store the current A/F ratio sensor output, and thereafter the control exits the routine. If it is determined at step S503 that T_2 seconds have passed after the affirmation of the detection-permitting conditions, then the control proceeds to the next step S504.

At step S504, the absolute value of a difference between the current FIC rate (FT_m) and the FIC rate (FT_{m-1}) previously stored at step S511 in a previous call of the routine (i.e., $\Delta FT_m = |FT_m - FT_{m-1}|$) is calculated, and the difference (or "variation") ΔFT_m is added to the cumulative value obtained up to the previous call of the routine (i.e., $\Sigma \Delta FT_{m-1}$), thereby updating the cumulative value $\Sigma \Delta FT$. When step S504 is performed for the first time after the conditions of steps S501 to S503 are satisfied, an initial value (=0) is substituted for the cumulative value ($\Sigma \Delta FT_{m-1}$) obtained up to the previous call of the routine (the initial value is used when the detection-permitting conditions are not satisfied at step S501).

At step S505, the absolute value of a difference between the A/F ratio sensor output (V_m) and the A/F ratio sensor output (V_{m-1}) previously stored at step S512 in a previous call of the routine (i.e., $\Delta V_m = |V_m - V_{m-1}|$) is calculated, and the difference (or "variation") ΔV_m is added to the cumulative value obtained up to the previous call of the routine (i.e., $\Sigma \Delta V_{m-1}$), thereby updating the cumulative value $\Sigma \Delta V$. When step S505 is performed for the first time after the conditions of steps S501 to S503 are satisfied, an initial value (=0) is substituted for the cumulative value ($\Sigma \Delta V_{m-1}$) obtained up to the previous call of the routine (the initial value is used when the detection-permitting conditions are not satisfied at step S501).

Step S506 counts the number of times the cumulation process has been performed at step S504 and at step S505. If the cumulation process has been performed m times, it is known that the cumulation of the variation ΔFT in the FIC rate and the variation ΔV in the A/F ratio sensor output has been performed for $T_s = m \times T_1$ (defined as "hitherto-performed cumulation time") in total. Assuming that the cumulation process is to be performed a total of M times (as counted at step S506 described later), the process of cumulating the variation ΔFT in the FIC rate and the variation ΔV in the A/F ratio sensor output must be performed for a predetermined time duration of $T_{\Sigma} = M \times T_1$ (defined as the "cumulation time"). Alternatively, it is possible to control the predetermined time duration (cumulation time) by measuring the duration T_{cont} of cumulation continued after the condition of step S503 is satisfied (i.e., T_2 seconds or more have passed).

The value of M representing the number of times the cumulation process is to be performed (or the cumulation time T_{Σ}), or the duration T_{Σ}' of cumulation to be continued after the condition of step S503 is satisfied, is prescribed so that the cumulation process will be performed for a period of time sufficiently longer than the variation cycle of the FIC rate and the variation cycle of the A/F ratio sensor output due to the feedback correction.

At step S507, it is determined whether or not the value of m (i.e., the number of times the cumulation process has been hitherto performed), as counted at step S506, is equal to or greater than the above-mentioned predetermined value M (i.e., the total number of times the cumulation process is to be performed). Alternatively, in the case where the cumulation time T_{Σ} is controlled by measuring the duration T_{cont} of cumulation after the condition of step S503 is satisfied, it is determined at step S507 whether or not the duration T_{cont} of cumulation after the condition of step S503 is satisfied is equal to or greater than the duration T_{Σ}' of cumulation to be continued after the condition of step S503 is satisfied.

It should be noted that the cumulation time T_{Σ} , during which the variation in the FIC rate and the variation ΔV in the A/F ratio sensor output are cumulated, need not be one continuous stretch of time. For example, if any of the detection-permitting conditions at step S501 is not satisfied before the hitherto-performed cumulation time T_s reaches the predetermined value T_{Σ} , the cumulative value S_1 (i.e., $\Sigma \Delta FT$) of the variation ΔFT in the FIC rate FT, the cumulative value S_3 (i.e., $\Sigma \Delta V$) of variation ΔV in the A/F ratio sensor output, the cumulation time T_s (defined in terms of m , i.e., a number of times the cumulation process has been performed, or in terms of T_{cont} , i.e., a duration of cumulation after the condition of step S503 is satisfied) and the like can be stored without being cleared, so that these values can be utilized when the process is resumed after the conditions of steps S501 to S503 are again satisfied, and the cumulation process of the variation ΔFT in the FIC rate FT and the variation ΔV in the A/F ratio sensor output as well as the counting of the number m or the duration T_{cont} of cumulation can be continued after the condition of step S503 is satisfied. Such resumption and continuation of the process will be described later in more detail. If the condition of step S507 is satisfied (i.e., if the cumulation process has been performed for the predetermined cumulation time T_{Σ}), then the control proceeds to step S508. If the condition of step S507 is not satisfied, step S511 (i.e., storing the current FIC rate FT) and step S512 (i.e., storing the current A/F ratio sensor output) are performed and thereafter the control exits the routine.

At step S508, a ratio P of the cumulative value $\Sigma \Delta FT$ of the variation ΔFT in the FIC rate and the cumulative value $\Sigma \Delta V$ of the variation ΔV in the A/F ratio sensor output (i.e., $P = \Sigma \Delta FT / \Sigma \Delta V$) is calculated.

At step S509, it is determined whether or not the ratio $P = \Sigma \Delta FT / \Sigma \Delta V$ calculated at step S508 exceeds a predetermined threshold value $P(\text{th})$. If the ratio P does not exceed the threshold value $P(\text{th})$, the A/F ratio sensor is determined as having normal characteristics (step S510b). If the ratio P exceeds the threshold value $P(\text{th})$, the A/F ratio sensor is determined as malfunctioning or having deteriorated characteristics (step S510a). When the A/F ratio sensor is determined as malfunctioning, a malfunction alert indicator within an instrument panel may be lit, for example.

The comparison between the ratio $P = \Sigma \Delta FT / \Sigma \Delta V$ against the threshold value $P(\text{th})$ can also be made as follows, for example: A reference ratio P_0 , defined as a ratio $\Sigma \Delta FT / \Sigma \Delta V$ of an A/F ratio sensor known to have normal response characteristics, is previously calculated. Then, it can be determined whether or not the ratio of the above-mentioned ratio P to the reference ratio P_0 exceeds the threshold value $P(\text{th})$.

EXAMPLE 5

As Example 5 of the present invention, a procedure for determining the deterioration in the response characteristics

of an A/F ratio sensor based on the cumulative value S_2 (i.e., ΣV) of the absolute values of the A/F ratio sensor output and the cumulative value S_3 (i.e., $\Sigma \Delta V$) of the variation ΔV in the A/F ratio sensor output will be described with reference to a flow diagram of FIG. 19 showing the A/F ratio sensor OUTPUT DETERIORATION (MALFUNCTIONING) DETERMINATION routine according to Example 5.

As shown in FIG. 19, at step S601, it is determined whether or not the conditions are satisfied for permitting the execution of the process for detecting the malfunctioning of the A/F ratio sensor ("detection-permitting conditions") The detection-permitting conditions may include, for example, that the travel speed of the automobile is within a predetermined range; that the rotation rate of the engine is within a predetermined range; that a feedback control is ongoing; and that other components and the system are free from malfunctions which may cause mis detections. Such detection-permitting conditions are checked by detecting the input signals from various sensors. If the detection-permitting conditions are satisfied, the control proceeds to the next step S602. If the detection-permitting conditions are not satisfied, the cumulative value S_2 ($=\Sigma V$) and S_3 ($=\Sigma \Delta V$) up to the previous call of the routine are cleared at step S612 and thereafter the control exits the routine.

The detection-permitting conditions must be satisfied in order to ensure that only accurate A/F ratio sensor output values and accurate values of variation therein are used for the calculation at each time interval T_1 .

The absolute value V of the A/F ratio sensor output and the variation ΔV in the A/F ratio sensor output are calculated at every predetermined time interval T_1 . The time interval T_1 is required to be sufficiently short relative to the variation cycle of A/F ratio sensor output so that an accurate cumulative value ΣV of the absolute value V of the A/F ratio sensor output and an accurate cumulative value $\Sigma \Delta V$ of the variation ΔV in the A/F ratio sensor output are obtained. At step S602, it is determined whether or not the routine cycle (i.e., as determined by a predetermined clock) is at a point where it coincides with a cycle defined by the time interval T_1 for calculating the absolute value V of the A/F ratio sensor output and the variation ΔV in the A/F ratio sensor output. If it is determined that the routine cycle does not coincide with the cycle defined by the time interval T_1 , the control exits the routine without performing any processes. If it is determined that the routine cycle coincides with the cycle defined by the time interval T_1 , the control proceeds to the next step S603.

The cycle of the malfunctioning detection routine must be prescribed as equal to or smaller than the time interval T_1 for calculating the absolute value V of the A/F ratio sensor output and the variation ΔV in the A/F ratio sensor output. Step S602 can be omitted in the case where the cycle of the malfunctioning detection routine is prescribed as equal to the time interval T_1 for calculating the absolute value V of the A/F ratio sensor output and the variation ΔV in the A/F ratio sensor output.

At step S603, it is determined whether or not T_2 seconds have passed since the detection-permitting conditions were confirmed to be satisfied at step S601. The reasons for performing the determination of step S603 are as follows: As described above, the detection-permitting conditions of step S601 must be satisfied in order to ensure that only accurate A/F ratio sensor output values V and accurate values of variation ΔV therein are used for the calculation at each time interval T_1 . In order to prevent the cumulation process from being influenced by a previous state where the detection-

permitting conditions were not satisfied, it is preferable to wait T_2 seconds after the detection-permitting conditions were satisfied before the absolute value V of the A/F ratio sensor output is added to the cumulative value ΣV (i.e., S_2) and the variation ΔV in the A/F ratio sensor output is added to the cumulative value $\Sigma \Delta V$ (i.e., S_3) and the variation ΔV in the A/F ratio sensor output is added to the cumulative value $\Sigma \Delta V$ (i.e., S_3). Thus, the accuracy of the cumulative data of the A/F ratio sensor output values V and the cumulative data of the variation ΔV in the A/F ratio sensor output is ensured. Preferably, T_1 and T_2 satisfy the relationship $T_1 \leq T_2$. If it is determined at step S603 that T_2 seconds have not passed after the affirmation of the detection-permitting conditions, step S609 is performed to store the current FIC rate FT and step S611 is performed to store the current A/F ratio sensor output, and thereafter the control exits the routine. If it is determined at step S603 that T_2 seconds have passed after the affirmation of the detection-permitting conditions, then the control proceeds to the next step S604.

At step S604, the absolute value V of the A/F ratio sensor output is calculated and added to the cumulative value obtained up to the previous call of the routine (i.e., ΣV_{m-1}), thereby updating the cumulative value ΣV . In the case where the A/F ratio sensor output corresponding to the stoichiometric A/F ratio is not zero, e.g., if the A/F ratio sensor output corresponding to the stoichiometric A/F ratio is designed to have a certain offset value, the offset value is eliminated before the cumulation calculation. If the control target of the A/F ratio is not the stoichiometric A/F ratio, the cumulation calculation can be directed to the cumulation of the absolute values of offsets from the target A/F ratio. When step S604 is performed for the first time after the conditions of steps S601 to S603 are satisfied, an initial value ($=0$) is substituted for the cumulative value (ΣV_{m-1}) obtained up to the previous call of the routine (the initial value is used when the detection-permitting conditions are not satisfied at step S601).

At step S605, the absolute value of a difference between the A/F ratio sensor output (V_m) and the A/F ratio sensor output (V_{m-1}) previously stored at step S611 in a previous call of the routine (i.e., $\Delta V_m = |V_m - V_{m-1}|$) is calculated, and the difference (or "variation") ΔV_m is added to the cumulative value obtained up to the previous call of the routine (i.e., $\Sigma \Delta V_{m-1}$), thereby updating the cumulative value $\Sigma \Delta V$. When step S605 is performed for the first time after the conditions of steps S601 to S603 are satisfied, an initial value ($=0$) is substituted for the cumulative value ($\Sigma \Delta V_{m-1}$) obtained up to the previous call of the routine (the initial value is used when the detection-permitting conditions are not satisfied at step S601).

Step S606 counts the number of times the cumulation process has been performed at step S604 and at step S605. If the cumulation process has been performed m times, it is known that the cumulation of the absolute value V of the A/F ratio sensor output and the variation ΔV in the A/F ratio sensor output has been performed for $T_s = m \times T_1$ (defined as "hitherto-performed cumulation time") in total. Assuming that the cumulation process is to be performed a total of M times (as counted at step S606 described later), the process of cumulating the absolute value V of the A/F ratio sensor output and the variation ΔV in the A/F ratio sensor output must be performed for a predetermined time duration of $T_{\Sigma} = M \times T_1$ (defined as the "cumulation time"). Alternatively, it is possible to control the predetermined time duration (cumulation time) by measuring the duration T_{cont} of cumulation continued after the condition of step S603 is satisfied (i.e., T_2 seconds or more have passed).

The value of M representing the number of times the cumulation process is to be performed (or the cumulation time T_{Σ}), or the duration T_{Σ}' of cumulation to be continued after the condition of step **S603** is satisfied, is prescribed so that the cumulation process will be performed for a period of time sufficiently longer than the variation cycle of the A/F ratio sensor output due to the feedback correction.

At step **S607**, it is determined whether or not the value of m (i.e., the number of times the cumulation process has been hitherto performed), as counted at step **S606**, is equal to or greater than the above-mentioned predetermined value M (i.e., the total number of times the cumulation process is to be performed).

Alternatively, in the case where the cumulation time T_{Σ} is controlled by measuring the duration T_{cont} of cumulation after the condition of step **S603** is satisfied, it is determined at step **S607** whether or not the duration T_{cont} of cumulation after the condition of step **S603** is satisfied is equal to or greater than the duration T_{Σ}' of cumulation to be continued after the condition of step **S603** is satisfied.

It should be noted that the cumulation time T_{Σ} , during which the absolute value V of the A/F ratio sensor output and the variation ΔV in the A/F ratio sensor output are cumulated, need not be one continuous stretch of time. For example, if any of the detection-permitting conditions at step **S601** is not satisfied before the hitherto-performed cumulation time T_s reaches the predetermined value T_{Σ} , the cumulative value S_2 (i.e., ΣV) of the absolute value V of the A/F ratio sensor output, the cumulative value S_3 (i.e., $\Sigma \Delta V$) of variation ΔV in the A/F ratio sensor output, the cumulation time T_s (defined in terms of m, i.e., a number of times the cumulation process has been performed, or in terms of T_{cont} , i.e., a duration of cumulation after the condition of step **S603** is satisfied) and the like can be stored without being cleared, so that these values can be utilized when the process is resumed after the conditions of steps **S601** to **S603** are again satisfied, and the cumulation process of the absolute value V of the A/F ratio sensor output and the variation ΔV in the A/F ratio sensor output as well as the counting of the number m or the duration T_{cont} of cumulation can be continued after the condition of step **S603** is satisfied. Such resumption and continuation of the process will be described later in more detail. If the condition of step **S607** is satisfied (i.e., if the cumulation process has been performed for the predetermined cumulation time T_{Σ}), then the control proceeds to step **S608**. If the condition of step **S607** is not satisfied, only step **S611** (i.e., storing the current A/F ratio sensor output) is performed and thereafter the control exits the routine.

At step **S608**, a ratio Q of the cumulative value ΣV of the absolute values of the A/F ratio sensor output and the cumulative value $\Sigma \Delta V$ of the variation in the A/F ratio sensor output (i.e., $Q = \Sigma V / \Sigma \Delta V$) is calculated.

At step **S609**, it is determined whether or not the ratio $Q = \Sigma V / \Sigma \Delta V$ calculated at step **S608** exceeds a predetermined threshold value $Q(th)$. If the ratio Q does not exceed the threshold value $Q(th)$, the A/F ratio sensor is determined as having normal characteristics (step **S610b**). If the ratio Q exceeds the threshold value $Q(th)$, the A/F ratio sensor is determined as malfunctioning or having deteriorated characteristics (step **S610a**). When the A/F ratio sensor is determined as malfunctioning, a malfunction alert indicator within an instrument panel may be lit, for example.

The comparison between the ratio $Q = \Sigma V / \Sigma \Delta V$ against the threshold value $Q(th)$ can also be made as follows, for example: A reference ratio Q_0 , defined as a ratio $\Sigma V / \Sigma \Delta V$ of

an A/F ratio sensor known to have normal response characteristics, is previously calculated. Then, it can be determined whether or not the ratio of the above-mentioned ratio Q to the reference ratio Q_0 exceeds the threshold value $Q(th)$.

EXAMPLE 6

As Example 6 of the present invention, a procedure for determining the deterioration in the response characteristics of an A/F ratio sensor based on the cumulative value S_1 (i.e., $\Sigma \Delta F$) of the variation ΔF in the FIC rate, the cumulative value S_2 (i.e., ΣV) of the absolute values of the A/F ratio sensor output and the cumulative value S_3 (i.e., $\Sigma \Delta V$) of the variation ΔV in the A/F ratio sensor output will be described with reference to a flow diagram of FIG. 20 showing the A/F ratio sensor OUTPUT DETERIORATION (MALFUNCTIONING) DETERMINATION routine according to Example 6.

As shown in FIG. 20, at step **S701**, it is determined whether or not the conditions are satisfied for permitting the execution of the process for detecting the malfunctioning of the A/F ratio sensor ("detection-permitting conditions"). The detection-permitting conditions may include, for example, that the travel speed of the automobile is within a predetermined range; that the rotation rate of the engine is within a predetermined range; that a feedback control is ongoing; and that other components and the system are free from malfunctions which may cause misdetections. Such detection-permitting conditions are checked by detecting the input signals from various sensors. If the detection-permitting conditions are satisfied, the control proceeds to the next step **S702**. If the detection-permitting conditions are not satisfied, the cumulative value S_1 ($= \Sigma \Delta F$), the cumulative value S_2 ($= \Sigma V$) and the cumulative value S_3 ($= \Sigma \Delta V$) up to the previous call of the routine are cleared at step **S714** and thereafter the control exits the routine.

The detection-permitting conditions must be satisfied in order to ensure that only accurate A/F ratio sensor output values and accurate values of variation therein are used for the calculation at each time interval T_1 .

The variation ΔF in the FIC rate, the absolute value V of the A/F ratio sensor output and the variation ΔV in the A/F ratio sensor output are calculated at every predetermined time interval T_1 . The time interval T_1 is required to be sufficiently short relative to the variation cycle of A/F ratio sensor output so that an accurate cumulative value $\Sigma \Delta F$ of the variation ΔF in the FIC rate, an accurate cumulative value ΣV of the absolute value V of the A/F ratio sensor output, and an accurate cumulative value $\Sigma \Delta V$ of the variation ΔV in the A/F ratio sensor output are obtained. At step **S702**, it is determined whether or not the routine cycle (i.e., as determined by a predetermined clock) is at a point where it coincides with a cycle defined by the time interval T_1 for calculating the variation ΔF in the FIC rate, the absolute value V of the A/F ratio sensor output, and the variation ΔV in the A/F ratio sensor output. If it is determined that the routine cycle does not coincide with the cycle defined by the time interval T_1 , the control exits the routine without performing any processes. If it is determined that the routine cycle coincides with the cycle defined by the time interval T_1 , the control proceeds to the next step **S703**.

The cycle of the malfunctioning detection routine must be prescribed as equal to or smaller than the time interval T_1 for calculating the variation ΔF in the FIC rate, the absolute value V of the A/F ratio sensor output, and the variation ΔV in the A/F ratio sensor output. Step **S702** can be omitted in

the case where the cycle of the malfunctioning detection routine is prescribed as equal to the time interval T_1 for calculating the variation ΔFT in the FIC rate, the absolute value V of the A/F ratio sensor output, and the variation ΔV in the A/F ratio sensor output.

At step **S703**, it is determined whether or not T_2 seconds have passed since the detection-permitting conditions were confirmed to be satisfied at step **S701**. The reasons for performing the determination of step **S703** are as follows: As described above, the detection-permitting conditions of step **S701** must be satisfied in order to ensure that only accurate values of variation ΔFT in the FIC rate, accurate A/F ratio sensor output values V , and accurate values of variation ΔV therein are used for the calculation at each time interval T_1 . In order to prevent the cumulation process from being influenced by a previous state where the detection-permitting conditions were not satisfied, it is preferable to wait T_2 seconds after the detection-permitting conditions were satisfied before the variation ΔFT in the FIC rate, the absolute value V of the A/F ratio sensor output, and the variation ΔV in the A/F ratio sensor output are added to the cumulative value $\Sigma \Delta FT$ (i.e., S_1), the cumulative value ΣV (i.e., S_2), and the cumulative value $\Sigma \Delta V$ (i.e., S_3), respectively. Thus, the accuracy of the cumulative data of the variation ΔFT in the FIC rate, the cumulative data of the A/F ratio sensor output values V , and the cumulative data of the variation ΔV in the A/F ratio sensor output is ensured. Preferably, T_1 and T_2 satisfy the relationship $T_1 \leq T_2$. If it is determined at step **S703** that T_2 seconds have not passed after the affirmation of the detection-permitting conditions, step **S712** is performed to store the current A/F ratio sensor output and step **S713** is performed to store the current FIC rate FT , and thereafter the control exits the routine. If it is determined at step **S703** that T_2 seconds have passed after the affirmation of the detection-permitting conditions, then the control proceeds to the next step **S704**.

At step **S704**, the absolute value V of the A/F ratio sensor output is calculated and added to the cumulative value obtained up to the previous call of the routine (i.e., ΣV_{m-1}), thereby updating the cumulative value ΣV . In the case where the A/F ratio sensor output corresponding to the stoichiometric A/F ratio is not zero, e.g., if the A/F ratio sensor output corresponding to the stoichiometric A/F ratio is designed to have a certain offset value, the offset value is eliminated before the cumulation calculation. If the control target of the A/F ratio is not the stoichiometric A/F ratio, the cumulation calculation can be directed to the cumulation of the absolute values of offsets from the target A/F ratio. When step **S704** is performed for the first time after the conditions of steps **S701** to **S703** are satisfied, an initial value (=0) is substituted for the cumulative value (ΣV_{m-1}) obtained up to the previous call of the routine (the initial value is used when the detection-permitting conditions are not satisfied at step **S701**).

At step **S705**, the absolute value of a difference between the A/F ratio sensor output (V_m) and the A/F ratio sensor output (V_{m-1}) previously stored at step **S711** in a previous call of the routine (i.e., $\Delta V_m = |V_m - V_{m-1}|$) is calculated, and the difference (or "variation") ΔV_m is added to the cumulative value obtained up to the previous call of the routine (i.e., $\Sigma \Delta V_{m-1}$), thereby updating the cumulative value $\Sigma \Delta V$. When step **S705** is performed for the first time after the conditions of steps **S701** to **S703** are satisfied, an initial value (=0) is substituted for the cumulative value ($\Sigma \Delta V_{m-1}$) obtained up to the previous call of the routine (the initial value is used when the detection-permitting conditions are not satisfied at step **S701**).

At step **S706**, the absolute value of a difference between the current FIC rate (FT_m) and the FIC rate (FT_{m-1}) previously stored at step **S713** in a previous call of the routine (i.e., $\Delta FT_m = |FT_m - FT_{m-1}|$) is calculated, and the difference (or "variation") ΔFT_m is added to the cumulative value obtained up to the previous call of the routine (i.e., $\Sigma \Delta FT_{m-1}$), thereby updating the cumulative value $\Sigma \Delta FT$. When step **S706** is performed for the first time after the conditions of steps **S701** to **S703** are satisfied, an initial value (=0) is substituted for the cumulative value ($\Sigma \Delta FT_{m-1}$) obtained up to the previous call of the routine (the initial value is used when the detection-permitting conditions are not satisfied at step **S701**).

Step **S707** counts the number of times the cumulation process has been performed at steps **S704**, **S705**, and **S706**. If the cumulation process has been performed m times, it is known that the cumulation of the variation ΔFT in the FIC rate, the absolute value V of the A/F ratio sensor output, and the variation ΔV in the A/F ratio sensor output has been performed for $T_s = m \times T_1$ (defined as "hitherto-performed cumulation time") in total. Assuming that the cumulation process is to be performed a total of M times (as counted at step **S707** described later), the process of cumulating the variation ΔFT in the FIC rate, the absolute value V of the A/F ratio sensor output, and the variation ΔV in the A/F ratio sensor output must be performed for a predetermined time duration of $T_\Sigma = M \times T_1$ (defined as the "cumulation time"). Alternatively, it is possible to control the predetermined time duration (cumulation time) by measuring the duration T_{cont} of cumulation continued after the condition of step **S703** is satisfied (i.e., T_2 seconds or more have passed).

The value of M representing the number of times the cumulation process is to be performed (or the cumulation time T_Σ), or the duration T_Σ' of cumulation to be continued after the condition of step **S703** is satisfied, is prescribed so that the cumulation process will be performed for a period of time sufficiently longer than the variation cycle of the FIC rate and the variation cycle of A/F ratio sensor output due to the feedback correction.

At step **S708**, it is determined whether or not the value of m (i.e., the number of times the cumulation process has been hitherto performed), as counted at step **S707**, is equal to or greater than the above-mentioned predetermined value M (i.e., the total number of times the cumulation process is to be performed). Alternatively, in the case where the cumulation time T_Σ is controlled by measuring the duration T_{cont} of cumulation after the condition of step **S703** is satisfied, it is determined at step **S708** whether or not the duration T_{cont} of cumulation after the condition of step **S703** is satisfied is equal to or greater than the duration T_Σ of cumulation to be continued after the condition of step **S703** is satisfied.

It should be noted that the cumulation time T_Σ , during which the variation ΔFT_m in the FIC rate, the absolute value V of the A/F ratio sensor output, and the variation ΔV in the A/F ratio sensor output are cumulated, need not be one continuous stretch of time. For example, if any of the detection-permitting conditions at step **S701** is not satisfied before the hitherto-performed cumulation time T_s reaches the predetermined value T_Σ , the cumulative value S_1 (i.e., $\Sigma \Delta FT$) of the variation ΔFT in the FIC rate, the cumulative value S_2 (i.e., ΣV) of the absolute value V of the A/F ratio sensor output, the cumulative value S_3 (i.e., $\Sigma \Delta V$) of the variation ΔV in the A/F ratio sensor output, the cumulation time T_s (defined in terms of m , i.e., a number of times the cumulation process has been performed, or in terms of T_{cont} , i.e., a duration of cumulation after the condition of step **S703** is satisfied) and the like can be stored without being cleared,

31

so that these values can be utilized when the process is resumed after the conditions of steps **S701** to **S703** are again satisfied, and the cumulation process of the variation ΔFT in the FIC rate, the absolute value V of the A/F ratio sensor output, and the variation ΔV in the A/F ratio sensor output as well as the counting of the number m or the duration T_{cont} of cumulation can be continued after the condition of step **S703** is satisfied. Such resumption and continuation of the process will be described later in more detail. If the condition of step **S708** is satisfied (i.e., if the cumulation process has been performed for the predetermined cumulation time T_{Σ}), then the control proceeds to step **S709**. If the condition of step **S708** is not satisfied, only step **S712** (i.e., storing the current A/F ratio sensor output) and step **S713** (i.e., storing the current FIC rate) are performed and thereafter the control exits the routine.

At step **S709**, a ratio P of the cumulative value $\Sigma\Delta FT$ of the variation in the FIC rate and the cumulative value $\Sigma\Delta V$ of the variation in the A/F ratio sensor output (i.e., $P=\Sigma\Delta FT/\Sigma\Delta V$) is calculated. Moreover, a ratio Q of the cumulative value ΔV of the absolute values of the A/F ratio sensor output and the cumulative value $\Sigma\Delta V$ of the variation in the A/F ratio sensor output (i.e., $Q=\Sigma V/\Sigma\Delta V$) is calculated.

At step **S710**, a product R of PQ derived at step **S708** is calculated [i.e., $R=PQ=(\Sigma\Delta FT/\Sigma\Delta V)\times(\Sigma V/\Sigma\Delta V)$], and it is determined whether or not the product R exceeds a predetermined threshold value $R(th)$. If the product R does not exceed the threshold value $R(th)$, the A/F ratio sensor is determined as having normal characteristics (step **S711b**). If the product R exceeds the threshold value $R(th)$, the A/F ratio sensor is determined as malfunctioning or having deteriorated characteristics (step **S711a**). When the A/F ratio sensor is determined as malfunctioning, a malfunction alert indicator within an instrument panel may be lit, for example.

The comparison between the product $R=(\Sigma\Delta FT\times\Sigma V)/(\Sigma\Delta V)^2$ against the threshold value $R(th)$ can also be made as follows, for example: A reference product R_0 , defined as a product $(\Sigma\Delta FT\times\Sigma V)/(\Sigma\Delta V)^2$ of an A/F ratio sensor known to have normal response characteristics, is previously calculated. Then, it can be determined whether or not the ratio of the above-mentioned product R to the reference product R_0 exceeds the threshold value $R(th)$.

EXAMPLE 7

As Example 7 of the present invention, a procedure for determining the deterioration in the response characteristics of an A/F ratio sensor based on the cumulative value S_1 (i.e., $\Sigma\Delta FT$) of the variation ΔFT in the FIC rate as in Example 1 will be described with reference to a flow diagram of FIG. 21 showing the A/F ratio sensor OUTPUT DETERIORATION (MALFUNCTIONING) DETERMINATION routine according to Example 7. The resent example illustrates an example where the cumulation time T_{Σ} , during which the variation ΔFT in the FIC rate is cumulated, is not one continuous stretch of time. The illustrated principle of resumption and continuation of the process can be similarly applied to the routines of the above-described Examples.

As shown in FIG. 21, at step **S801**, it is determined whether or not the conditions are satisfied for permitting the execution of the process for detecting the malfunctioning of the A/F ratio sensor (hereinafter such conditions are referred to as "detection-permitting conditions"). The detection-permitting conditions may include, for example, that the travel speed of the automobile is within a predetermined range; that the rotation rate of the engine is within a predetermined range; that a feedback control is ongoing; and

32

that other components and the system are free from malfunctions which may cause mis detections. Such detection-permitting conditions are checked by detecting the input signals from various sensors. If the detection-permitting conditions are satisfied, the control proceeds to the next step **S802**. If the detection-permitting conditions are not satisfied, the cumulative value S_1 ($=\Sigma\Delta FT$) up to the previous call of the routine is cleared at step **S814** and thereafter the control exits the routine.

The detection-permitting conditions must be satisfied in order to ensure that only accurate FIC rate values are used for the calculation of the variation ΔFT in the FIC rate at each time interval T_1 .

The variation ΔFT in the FIC rate is calculated at every predetermined time interval T_1 . The time interval T_1 is required to be sufficiently short so that the detection of the variation in the FIC rate can be accurate. At step **S802**, it is determined whether or not the routine cycle (i.e., as determined by a predetermined clock) is at a point where it coincides with a cycle defined by the time interval T_1 for calculating the variation ΔFT in the FIC rate. If it is determined that the routine cycle does not coincide with the cycle defined by the time interval T_1 , the control exits the routine without performing any processes. If it is determined that the routine cycle coincides with the cycle defined by the time interval T_1 , the control proceeds to the next step **S803**.

The cycle of the malfunctioning detection routine must be prescribed as equal to or smaller than the time interval T_1 for calculating the variation ΔFT in the FIC rate. Step **S802** can be omitted in the case where the cycle of the malfunctioning detection routine is prescribed as equal to the time interval T_1 for calculating the variation ΔFT in the FIC rate.

At step **S803**, it is determined whether or not T_2 seconds have passed since the detection-permitting conditions were confirmed to be satisfied at step **S801**. The reasons for performing the determination of step **S803** are as follows: As described above, the detection-permitting conditions of step **S801** must be satisfied in order to ensure that only accurate FIC rate values are used for the calculation of the variation ΔFT in the FIC rate at every time interval T_1 . In order to prevent the cumulation process from being influenced by a previous state where the detection-permitting conditions were not satisfied, it is preferable to wait T_2 seconds after the detection-permitting conditions were satisfied before the variation ΔFT in the FIC rate is added to the cumulative value $\Sigma\Delta FT$ (i.e., S_1). Thus, the accuracy of the cumulative data of the variation ΔFT in the FIC rate is ensured. Preferably, T_1 and T_2 satisfy the relationship $T_1 \leq T_2$. If it is determined at step **S803** that T_2 seconds have not passed after the affirmation of the detection-permitting conditions, step **S813** is performed to store the current FIC rate FT , and thereafter the control exits the routine. If it is determined at step **S803** that T_2 seconds have passed after the affirmation of the detection-permitting conditions, then the control proceeds to the next step **S804**.

At step **S804**, the absolute value of a difference between the current FIC rate (FT_m) and the FIC rate (FT_{m-1}) previously stored at step **S813** in a previous call of the routine (i.e., $\Delta FT_m=|FT_m-FT_{m-1}|$) is calculated, and the difference (or "variation") ΔFT_m is added to the cumulative value obtained up to the previous call of the routine (i.e., $\Sigma\Delta FT_{m-1}$) thereby updating the cumulative value $\Sigma\Delta FT$. When step **S804** is performed for the first time after the conditions of steps **S801** to **S803** are satisfied, an initial value ($=0$) is substituted for the cumulative value ($\Sigma\Delta FT_{m-1}$) obtained up to the previous call of the routine (the initial value is used when the detection-permitting conditions are not satisfied at step **S801**).

Step **S805** measures the time duration t_1 after the affirmation of the condition of step **S803** (i.e., that T_2 seconds or more have passed since the detection-permitting conditions were satisfied at step **S801**).

Step **S806** determines whether or not the duration t_1 has reached a predetermined time T_3 . If the duration t_1 has not reached the predetermined time T_3 , only step **S813** (i.e., storing the current FIC rate) is performed and the control returns to step **S801** so that the routine is repeated. In other words, the calculation of ΔFT is performed to keep updating the cumulative value $\Sigma\DeltaFT$ (steps **S801** to **S805**) until the duration t_1 reaches the predetermined time T_3 . If it is determined at step **S806** that the duration t_1 has reached the predetermined time T_3 , the control proceeds to step **S807**.

At step **S807**, the hitherto-obtained cumulative value $\Sigma\DeltaFT$, i.e., $\Sigma\DeltaFT$ obtained for the last T_3 seconds, is added to the $\Sigma\DeltaFT$ from the previous sets of T_3 seconds, thereby updating the value of $\Sigma(\Sigma\DeltaFT)$. When the calculation of the cumulative value $\Sigma\DeltaFT$ for T_3 seconds at step **S807** is performed for the first time, an initial value (=0) is substituted for the “cumulative value $\Sigma\DeltaFT$ from the previous T_3 seconds” (the initial value is used when the detection-permitting conditions are not satisfied at step **S801**).

At step **S808**, the number of times step **S807** has been performed is counted by using e.g., a counter, so as to increase a count number C_1 . At step **S809**, the time t_1 measured at step **S805** is cleared.

At step **S810**, it is determined whether or not the count number C_1 has exceeded a predetermined value N . If the count number C_1 has not exceeded a predetermined value N , only step **S813** (i.e., storing the current FIC rate) is performed and thereafter the control returns to step **S801** to repeat the routine. In other words, the cumulation of $\Sigma\DeltaFT$ for T_3 seconds is performed to give $\Sigma(\Sigma\DeltaFT)$ (steps **S801** to **S809**) until the count number C_1 reaches the predetermined number N . If it is determined at step **S810** that the count number C_1 has reached the predetermined number N , the control proceeds to step **S811**.

At step **S811**, the hitherto-obtained cumulative value $\Sigma(\Sigma\DeltaFT)$, i.e., the cumulative value of ΔFT for $T_3 \times C_1$ seconds, is compared with a predetermined threshold value $\Sigma(\Sigma\DeltaFT)_{th}$. If the cumulative value $\Sigma(\Sigma\DeltaFT)$ has not exceeded the threshold value $\Sigma(\Sigma\DeltaFT)_{th}$, the A/F ratio sensor is determined as having normal characteristics (step **S812b**). If the cumulative value $\Sigma(\Sigma\DeltaFT)$ has exceeded the threshold value $\Sigma(\Sigma\DeltaFT)_{th}$, the A/F ratio sensor is determined as malfunctioning or having deteriorated characteristics (step **S812a**). When the A/F ratio sensor is determined as malfunctioning, a malfunction alert indicator within an instrument panel may be lit, for example.

In the present example, if any of the detection-permitting conditions at step **S801** is not satisfied before the count number C_1 of the counter reaches the predetermined value N , the cumulative value S_1 (i.e., $\Sigma\DeltaFT$) for T_3 seconds, which was still under way at that point in time (when $t_1 < T_3$), is cleared at step **S814**; however, the cumulation of the past cumulative values $\Sigma(\Sigma\DeltaFT)$ is still stored without having been cleared. Therefore, the “cumulation for T_3 seconds” (for obtaining $\Sigma\DeltaFT$) can be resumed after the conditions of step **S801** are again satisfied, to be continued until the count number C_1 reaches the predetermined number N . Thus, the cumulation of the variation in the FIC rate can be performed for $C_1 \times T_3$ seconds = T_Σ .

In the present example, by prescribing T_3 at a short value relative to the predetermined cumulation time T_Σ , it becomes possible to efficiently perform the cumulation of the varia-

tion in the FIC rate even if the detection-permitting conditions of step **S801** are repetitively satisfied or dissatisfied, thereby enabling an early detection of the malfunctioning of the A/F ratio sensor.

An early detection of the malfunctioning of an A/F ratio sensor can also be achieved by methods other than the method of Example 7, e.g., by performing discontinuous or intermittent cumulation processes of the variation in the FIC rate.

The discontinuous cumulation process of the variation in the FIC rate according to the present example, which is performed until reaching the predetermined cumulation time T_Σ , can be applied to the other Examples of the present invention. For example, the discontinuous cumulation process can be applied in Example 2 by replacing steps **S301** to **S306** (FIG. 16) with steps **S801** to **S810** of Example 7.

Thus, the A/F ratio sensor deterioration detection device has been described with respect to illustrative but non-limiting Examples. For example, it is possible to determine the deterioration of the A/F ratio sensor by combining any of two or more methods described in Examples 1 to 6, rather than employing each method alone. The specific configuration of the A/F ratio sensor deterioration detection device can be adopted by, e.g., combining one or more the determination methods in the respective Examples, depending on the type and the degree of deterioration of the subject A/F ratio sensor.

Thus, in an A/F ratio control apparatus employing an A/F ratio sensor capable of continuously detecting an A/F ratio within a broad range of values including the stoichiometric A/F ratio, the invention described herein advantageously provides a device for achieving an early detection of the deterioration of the A/F ratio sensor without relying on the sensor characteristics in control ranges outside the stoichiometric value.

Various other modifications will be apparent to and can be readily made by those skilled in the art without departing from the scope and spirit of this invention. Accordingly, it is not intended that the scope of the claims appended hereto be limited to the description as set forth herein, but rather that the claims be broadly construed.

What is claimed is:

1. A device for determining deterioration of an air-fuel ratio sensor, the device comprising:

an air-fuel ratio sensor provided in an exhaust passage of an internal combustion engine, the air-fuel ratio sensor being capable of continuously detecting a broad range of air-fuel ratios including a stoichiometric air-fuel ratio;

air-fuel ratio feedback control means for feedback controlling a fuel injection amount based on a difference between an output of the air-fuel ratio sensor and a target output corresponding to a target air-fuel ratio so that an air-fuel ratio of a gaseous mixture substantially equals the target air-fuel ratio, the gaseous mixture being supplied to the engine;

variation cumulative value calculation means for cumulating, while the air-fuel ratio feedback control is being performed by the air-fuel ratio feedback control means, a variation ΔFT in a fuel injection correction amount, thereby calculating a cumulative variation value $\Sigma\DeltaFT$ for a predetermined period; and

deterioration determination means for determining that the air-fuel ratio sensor is deteriorated when the cumulative variation value $\Sigma\DeltaFT$ calculated by the variation cumulative value calculation means exceeds a predetermined value.

35

2. A device for determining deterioration of an air-fuel ratio sensor, the device comprising:

an air-fuel ratio sensor provided in an exhaust passage of an internal combustion engine, the air-fuel ratio sensor being capable of continuously detecting a broad range of air-fuel ratios including a stoichiometric air-fuel ratio;

air-fuel ratio feedback control means for feedback controlling a fuel injection amount based on a difference between an output of the air-fuel ratio sensor and a target output corresponding to a target air-fuel ratio so that an air-fuel ratio of a gaseous mixture substantially equals the target air-fuel ratio, the gaseous mixture being supplied to the engine;

output cumulative value calculation means for cumulating, while the air-fuel ratio feedback control is being performed by the air-fuel ratio feedback control means, at least one of an absolute value of output of the air-fuel ratio sensor and a difference between the output of the air-fuel ratio sensor and the target output, thereby calculating a cumulative output value ΣV for a predetermined period; and

deterioration determination means for determining that the air-fuel ratio sensor is deteriorated when the cumulative output value ΣV calculated by the output cumulative value calculation means exceeds a predetermined value.

3. A device for determining deterioration of an air-fuel ratio sensor, the device comprising:

an air-fuel ratio sensor provided in an exhaust passage of an internal combustion engine, the air-fuel ratio sensor being capable of continuously detecting a broad range of air-fuel ratios including a stoichiometric air-fuel ratio;

air-fuel ratio feedback control means for feedback controlling a fuel injection amount based on a difference between an output of the air-fuel ratio sensor and a target output corresponding to a target air-fuel ratio so that an air-fuel ratio of a gaseous mixture substantially equals the target air-fuel ratio, the gaseous mixture being supplied to the engine;

variation cumulative value calculation means for cumulating, while the air-fuel ratio feedback control is being performed by the air-fuel ratio feedback control means, a variation ΔV in output of the air-fuel ratio sensor, thereby calculating a cumulative variation value $\Sigma \Delta V$ for a predetermined period; and

deterioration determination means for determining that the air-fuel ratio sensor is deteriorated when the cumulative variation value $\Sigma \Delta V$ calculated by the variation cumulative value calculation means exceeds a predetermined value.

4. A device for determining deterioration of an air-fuel ratio sensor, the device comprising:

an air-fuel ratio sensor provided in an exhaust passage of an internal combustion engine, the air-fuel ratio sensor being capable of continuously detecting a broad range of air-fuel ratios including a stoichiometric air-fuel ratio;

air-fuel ratio feedback control means for feedback controlling a fuel injection amount based on a difference between an output of the air-fuel ratio sensor and a target output corresponding to a target air-fuel ratio so that an air-fuel ratio of a gaseous mixture substantially equals the target air-fuel ratio, the gaseous mixture being supplied to the engine;

36

variation cumulative value calculation means for cumulating, while the air-fuel ratio feedback control is being performed by the air-fuel ratio feedback control means, a variation ΔF in a fuel injection correction amount and a variation ΔV in output of the air-fuel ratio sensor, thereby respectively calculating a cumulative variation value $\Sigma \Delta F$ and a cumulative variation value $\Sigma \Delta V$ for a predetermined period; and

deterioration determination means for determining if the air-fuel ratio sensor is deteriorated based on a ratio between the cumulative variation value $\Sigma \Delta F$ and the cumulative variation value $\Sigma \Delta V$ calculated by the variation cumulative value calculation means.

5. A device for determining deterioration of an air-fuel ratio sensor, the device comprising:

an air-fuel ratio sensor provided in an exhaust passage of an internal combustion engine, the air-fuel ratio sensor being capable of continuously detecting a broad range of air-fuel ratios including a stoichiometric air-fuel ratio;

air-fuel ratio feedback control means for feedback controlling a fuel injection amount based on a difference between an output of the air-fuel ratio sensor and a target output corresponding to a target air-fuel ratio so that an air-fuel ratio of a gaseous mixture substantially equals the target air-fuel ratio, the gaseous mixture being supplied to the engine;

variation cumulative value calculation means for cumulating, while the air-fuel ratio feedback control is being performed by the air-fuel ratio feedback control means, output V of the air-fuel ratio sensor and a variation ΔV in the output of the air-fuel ratio sensor, thereby respectively calculating a cumulative output value ΣV and a cumulative variation value $\Sigma \Delta V$ for a predetermined period; and

deterioration determination means for determining if the air-fuel ratio sensor is deteriorated based on a ratio between the cumulative output value ΣV and the cumulative variation value $\Sigma \Delta V$ calculated by the variation cumulative value calculation means.

6. A device for determining the deterioration of an air-fuel

ratio sensor according to claim 5 further comprising variation cumulative value calculation means for cumulating, while the air-fuel ratio feedback control is being performed by the air-fuel ratio feedback control means, a variation ΔF in a fuel injection correction amount and a variation ΔV in output of the air-fuel ratio sensor, thereby respectively calculating a cumulative variation value $\Sigma \Delta F$ and a cumulative variation value $\Sigma \Delta V$ for a predetermined period,

wherein the deterioration determination means determines if the air-fuel ratio sensor is deteriorated based on a ratio between the cumulative output value ΣV and the cumulative variation value $\Sigma \Delta V$ and a ratio between the cumulative variation value $\Sigma \Delta F$ and the cumulative variation value $\Sigma \Delta V$.

7. A device for determining the deterioration of an air-fuel

ratio sensor according to claim 6, wherein the deterioration determination means determines if the air-fuel ratio sensor is deteriorated based on a product of a ratio between the cumulative output value ΣV and the cumulative variation value $\Sigma \Delta V$ and a ratio between the cumulative variation value $\Sigma \Delta F$ and the cumulative variation value $\Sigma \Delta V$.
